2,099,429

AUTOMATIC TELEPHONE SYSTEM

John E. Ostline, Berwyn, Ill., assignor to Associated Electric Laboratories, Inc., Chicago, Ill., a corporation of Delaware

Application May 7, 1934, Serial No. 724,238

18 Claims. (Cl. 179—17)

The present invention relates in general to automatic telephone systems, but more in particular to systems suitable for installation in small towns and villages. An automatic system of this type is generally known as a community automatic exchange or C.A.X. In these systems it is the usual practice to provide for multi-station party lines having either bridged or grounded ringing circuits, or combinations of each and the subscribers are signalled by means of code ringing equipment. The exchanges are also usually unattended, but are provided with trunking facilities to distant exchanges.

One of the objects of the present invention is to economically provide a telephone system of this character capable of serving a community requiring a system of a capacity of as many as two hundred lines and trunks.

One of the outstanding features of the invention relates to the employment of finder connector links of a novel type common to all lines and trunks of the system and employed to connect any calling line or trunk through to a desired called line.

Other features have to do with the novel manner in which a finder connector link is employed to establish local, reverting call, P.B.X. and toll trunk connections, respectively.

The invention is disclosed in seven sheets of drawings, numbered Figs. 1 to 7, respectively. The drawings should be arranged with Fig. 1 to the left of Fig. 2, Fig. 3 to the right of Fig. 2, Fig. 6 immediately below Fig. 3, Fig. 5 to the immediate left of Fig. 6, Fig. 4 below Fig. 1, and with Fig. 7 to the left of Fig. 1, and with the corresponding lines of the various adjacent figures in alignment. With the drawings so arranged they diagrammatically disclose sufficient circuits and apparatus to enable the invention to be understood when considered in conjunction with the description which follows.

Considering the drawings more in detail, Fig. 1 shows a calling party line and its individual line equipment SLE, and the line equipment TLE of a trunk line which is substantially like the subscriber's line equipment SLE. To the right of the trunk and subscriber's line equipment shown are bank contacts and the wipers of a finder portion of apparatus and equipment constituting one of a plurality of finder connector links of the

system. The operating and release magnets of the finder are shown in the lower central portion of the figure.

Fig. 2 discloses the central portion of the finder connector link and at the bottom of the figure are grouped the operating and release magnets and the special rotary control bank and wiper of the connector mechanism of the link.

Fig. 3 shows the remainder of the link circuit, the wipers and certain of the bank contacts of the connector, and in the lower portion of this figure discloses the operating and release magnets and the wipers and banks of the class and code switch CC of the link. The equipment to the right of the figure comprises a subscriber's line equipment SLE' and its associated party line, and also an alarm line equipment ALE which may be seized by a toll operator for obtaining supervision of possible trouble conditions existing in the community automatic exchange.

In Fig. 4 is shown an allotter comprising an allotter control relay group designated generally ACR and a second group of link selecting relays designated LSR. In the lower portion of the figure are two other relay groups, one comprising a group of group marking relays GMR and the other comprising a group of finder control relays FCR.

The equipment in Fig. 5 in the main consists of a combination of code interrupter relays CI employed in generating the codes required to signal the various stations on party lines. In the lower part of this figure there are also a number of relays designated generally as ARG which function under certain abnormal conditions to register alarm conditions in the alarm line equipment ALE of Fig. 3.

Fig. 6 shows the ringing equipment RE employed.

In Fig. 7 the majority of the circuits shown comprise a trunk TR and its associated equipment terminating in a distant exchange. In the lower right-hand corner of this figure, however, is shown a group of time cut-off relays TCO employed to prevent various pieces of equipment being held for an undue period.

Throughout the drawings numerous types of relays, well known in the automatic telephone art, are shown. Slow-to-operate relays are shown having a full-black upper section. Slow-release

relays are shown having a cross-hatched section. Shunt field relays are shown by representing their two windings on separate cores included in a shunted magnetic circuit. The subscribers' line relays are of this type. These relays only operate when both windings are energized. A number of three-pole relays of the type covered by Pye Patent No. 1,673,884, issued June 19, 1928 are also employed, and these are designated with a core equipped with a bar magnetically separating the two windings of the relay. These relays only operate when both windings are energized, but will then hold through one winding. The test relay 175 is an example of this type. The finder and connector switch mechanisms, respectively, are of the well known Strowger type arranged with two sets of wipers giving these switches access to two groups of 100 lines each. The switch employed as a connector is also provided with an auxiliary rotary control bank RCB and an associated wiper RCW which are employed to produce an automatic trunk hunting movement of the connector when the switch is positioned opposite P.B.X. and toll trunk levels of its bank contacts.

The class and code switch mechanisms shown in the lower portion of Fig. 3 are of the well known pawl and ratchet type arranged to advance its wipers in a step by step manner when its operating magnet is intermittently energized, and to restore its wipers through the medium of a spring, tensioned during the advance, upon operation of the release magnet of the switch.

In brief, the operation of the system is as follows:

When a calling subscriber initiates a call the test conductor of the calling line is marked with calling potential and the group in which the calling line is located is marked on the contact of one of the group marking relays GMR associated with the allotter, and the connecting relay 165 of the link operates to cause the finder control relays FCR, also associated with the allotter, to interact with the vertical magnet of the finder of the link to cause the finder to elevate its wipers opposite the group in which the calling line is located. The finder control relays at the same time operate the group marking relays GMR in a definite sequence, and when the one is operated which has a potential on one of its contacts the control of these relays by the finder control relay ceases and a change-over relay of the finder control relay group operates to bring about the line hunting or rotary movement of the finder. When the marked line is found the test relay 175 operates to stop the finder and to cut the calling line through to the link circuit. The calling subscriber now receives dial tone and proceeds to transmit the digits constituting the called subscriber's number. The subscriber dials four digits to complete a connection to the called line. The first digit transmitted operates the class and code switch CC to determine in which hundred group the called line is located and to also determine on which side of the line the ringing current is to be transmitted. The class and code switch is then released. The next two digits transmitted position the wipers of the connector into engagement with the desired line. The fourth digit transmitted then positions the class and code switch CC to determine the code to be transmitted to the called line. The equipment for generating the code is obviously disclosed in Fig. 5 and the code actually transmitted

is determined by the position of the wipers 316 and 317 of the switch CC.

Incoming trunk calls come in over line equipment the same as provided for local subscribers' lines and connections are established in the same manner except that on this type of calls the called line instead of receiving talking potential from relays in the link is cut through to relays in the trunk circuit.

On outgoing trunk calls to a distant exchange the single digit 8, 9 or 0 is dialled and the impulses of this digit operate the class and code switch seven steps after which a relay in the link operates and switches the remaining impulses of the digit to the vertical magnet of the connector of the link to connect the switch wipers opposite the desired trunk level. The switch then automatically rotates under control of its rotary control wiper to connect with the first idle trunk.

On P. B. X. trunk calls the connector switch, after having its wipers positioned on the contacts of the first line of the P. B. X. group by the transmitted impulses, rotates under control of its rotary control wiper to find an idle line as in outgoing trunk calls.

In establishing reverting calls the subscriber dials the regular four digit number of the called station and upon receipt of the busy tone hangs up his receiver. During the ringing operation of the called station the calling subscriber receives a characteristic ring back tone or hears the same code as is being received at the called station, and upon cessation of the ringing of his own signal is advised that the called subscriber has responded. In reverting call connections the link circuit releases as soon as the called party responds and the calling and called subscribers on the same line receive talking battery from the line relay of such line.

A more detailed description of the operation of the system will now be given.

Local connections

In order to describe in detail the operation of the system it will first be assumed that the subscriber at station 5951 desires to establish a connection with a party at station 2645. When the subscriber at station 5951 removes his receiver a circuit for the line relay 131 is completed. This circuit extends from ground through the left winding of relay 131, through the contacts 136 of cut-off relay 135, line conductor 128, the station equipment, line conductor 129, the contacts 137 of the cut-off relay 135 and through the right-hand winding of line relay 131 to battery. The line relay 131, upon operating, at its armature 133 disconnects the cut-off relay 135 from the test lead 1 of the connector multiple of the calling line and instead connects ground potential thereto, thereby rendering the calling line busy to other subscribers. The relay 131, also, at its contact 132 connects the cut-off relay 135, via contacts 142, to the test terminal 160 of the finder bank to mark #5951 as a calling line, and at contacts 134 applies ground potential to start conductor 410 via armature 143 and its resting contact, thereby marking the group in which the calling line is associated in the allotter.

The ground potential applied to the start conductor 410 extends via conductor 457, resistance R43, conductor 456, contacts 482' of relay 482, conductor 408', and the winding of relay 4001 to battery. The relay 4001, accordingly operates and at its contacts 4003 completes a locking cir-

cuit for itself excluding the contacts 482'. This circuit includes conductor 408, the lower contacts of relay 423, and conductor 4007.

The inclusion of relay 4001 in a locking circuit 5 excluding contacts of relay 4002 prevents a premature release of relay 4001 which might otherwise occur should a succeeding call be initiated over a line of the first hundred group immediately following the operation of relay 4001. When a call 10 is initiated by a line of the first hundred group relay 4002 is operated instead of relay 4001 and at its contacts 482' prevents a subsequent calling line of the second hundred group from interfering with calls initiated over the first hundred group.

15 The relay 4001, at armature 4004 transfers the connection of the winding of relay 482 from association with group marking relay contacts of the first hundred group of calling line start conductors and associates it with the contacts of the 20 group marking relays associated with the second hundred group of start conductors. The relay 4001 also, at contacts 4005 prepares a point in the operating circuit of wiper switching relay 174, and at contacts 4006 closes a circuit for the allotter control relay 418. This circuit extends from ground, supplied through the contacts 4008, conductor 4008, contacts 417 of slow-release relay 414, the contacts 460 of all link busy relay 431, and through the lower winding of relay 418 to 30 battery. The relay 418, upon energizing, at contacts 420 applies ground potential to conductor 462 to maintain the slow release relay 435 energized independently of armature 434, at armature 421 applies ground potential to 35 the conductor 463, and via contacts 415 to relay 411 of the timing relays 411, 413 and 414, and at its contacts 422 applies ground potential via contacts 429 to conductor 455, extending to the connecting relay of the link at the time associated 40 with the allotter. In the present example the circuit extends via contacts 440, conductor 402 and through the winding of connecting relay 165 to battery.

Upon an inspection of Fig. 4 it will be observed 45 that the present system is assumed to be provided with twelve link circuits and that only the first, second, and twelfth link selecting relays have been shown. The first of the twelve links is the one shown in the drawings to have been preselected 50 at the time the call under consideration was initiated. As long as one or more of the link circuits are idle, the all link busy relay 431 is energized over the common all link busy conductor 403, from ground supplied from one or more of 55 the multiple circuits extending from the idle link circuits. One of these circuits may be traced from grounded armature 169 and its resting contact, conductor 121, contacts 244, off-normal spring ON22 at its resting contact, conductor 120, off- 60 normal spring ON12 and its resting contact, the busy keys springs, contacts 185, the all link busy conductor 403, and the winding of relay 431 to battery. Since a like circuit extends via each idle link and into connection with the all link busy conductor 403 the relay 431 only deenergizes at such time as all of the links are busy. The relay 431 at contacts 433 closes a point in a circuit including the guard conductor 401 of the preselected link and which later becomes effective in case 70 the calling line is not found within a predetermined time, as will be described later. The relay 431 at contacts 460 closes a point in the pick-up circuit for relay 418, at armature 434 removes ground from the timing conductor 463 so as to 75 place this conductor and the timing relays 411,

413, and 414 under control of relay 418, and connects ground to conductor 462. This ground potential, extends to the winding of slow release relay 435, through the lower winding of relay 438, the break contacts of this latter relay, to the 5 lower break contacts of link selecting relay 446, the contacts 444 of relay 439, and the lower winding of this relay, in multiple with resistance R45. Relay 435, upon operating at its contacts 437, opens the initial operating circuit of link selecting relay 439, and at contacts 436 prepares a locking circuit for relay 438. The relay 439 is initially energized from ground on the front contact of armature 434 supplied to the upper winding of relay 439 via contacts 437 and conductor 453 and 10 through the upper winding of relay 427, contacts 432, conductor 454. The relay 439 at contacts 440 closes a point in the operating circuit of the link connecting relay 165, at its contacts 442 prepares a point in the circuit extending to the guard 20 conductor 401, at its contacts 443 prepares a circuit for the link selecting relay 446, at its contacts 445 opens a point in the locking circuit of link selecting relay 447, and at its contacts 444 completes a locking circuit for itself. This 25 circuit includes the lower winding of relay 439 and resistance R45 in multiple, contacts 444, the lower break contacts of relay 446, conductor 451, the break contacts of relay 438, the lower winding of this relay, the winding of slow release relay 30 435, and the contact and armature 434 of relay 431 and ground. Upon completion of the circuit the relay 435 operates and at its contacts 437 breaks the initial operating circuit of relay 439 and at its contacts 436 prepares a locking circuit 35 for relay 438.

Since the first link is the one preselected, due to the link selecting relay 439 being in energized position, the relay 418, upon energization, completes, in this case, the circuit for energizing the 40 link connecting relay 165. This circuit extends from ground through contacts 422 of relay 418, contacts 429, conductor 455, contacts 440, start conductor 402, and the winding of relay 165 to 45 battery. The start relay 418 at its contacts 421 grounds conductor 463 to energize the timing relay 411; at contacts 420 applies ground to conductor 462 so as to hold relay 435 and the link selecting relay 439 energized independent of the 50 all link busy relay 431 should the link selected 55 be the last idle one of the group; and at contacts 419 completes a circuit for itself independent of the contacts 460 of relay 431, and also independent of the contacts 417 of timing relay 414. The relay 411 operates and, after an interval, completes the circuit of slow to operate relay 413 and this relay in turn completes the operating circuit of slow release relay 414. The relay 414, upon operating, at its contacts 415 interrupts the circuit of relay 411 which accordingly deenergizes, 60 and at contacts 416 closes a point in a link selecting circuit which will be completed later if the selected link fails to find the calling line within a predetermined time. The relay 414 also, at its contacts 417, opens a point in the initial operating circuit of relay 418, making the holding up of this relay dependent on the non-operated condition of the cut-through relay 423. The relay 413, upon restoring, causes its weighted spring to vibrate and in so doing alternately opens and 70 closes the circuit of slow to operate relay 413. Due to its slow to release characteristic the relay 413 remains operated during the vibration of armature 412. When the armature 412 finally comes to rest, in its deenergized position, relay 75

413 restores. If the finder has not by this time succeeded in finding the calling line or some other line has in the meantime effected the grounding of conductor 4008 relay 418 will still be energized. Under these circumstances the relay 413 completes a circuit from ground at contacts 421 of the start relay, through the armature and resting contact of relay 413, contacts 416, 433, 442, conductor 448, the upper break contacts of relay 447, guard conductor 401, contacts 443, the upper winding of link selecting relay 446, conductor 454, contacts 432, and the upper winding of relay 427 and resistance R48 in multiple to battery. The relay 446, upon operating, at its lower break contacts interrupts the locking circuit of the link selecting relay 439, which accordingly restores and disassociates the first link from operative relation with the allotter. The relay 446, at its lower make contacts now completes a locking circuit for itself, at its contacts 443' prepares a point in the operating circuit of the next link selecting relay of the group, at contacts 442' closes a point in a circuit including the guard conductor of the second of the links, at contacts 441' opens a point in the guard conductor of the subsequent or third link, and at contacts 440' connects the start lead of the second link to the common start conductor 455.

In the link circuit the relay 165, upon becoming energized over the previously traced circuit, at contacts 124 and 166 applies ground potential to the test and polarizing windings of test relay 175, at contacts 164 applies ground potential to conductor 107, and at contacts 167 closes a point in the operating circuit of wiper switching relay 174. The relay 165 also, at contacts 168, closes a point in the operating circuit of cut-through relay 423, at armature 169 removes ground potential from conductor 121, and applies ground potential to conductor 406 and through the contacts 495 of interrupter relay 482 and the winding of relay 481 to battery. The relay 165 finally, at its contacts 170 applies ground potential to conductor 403 to replace that removed therefrom as a result of the operation of armature 169, to hold the all link busy relay 431 operated until the calling line is found if this is the last of the idle links; and at contacts 171, 172, and 173 operatively associates the vertical and rotary magnets 126 and 125 and the associated control conductor 127 with leads 408, 405, and 407, extending to the finder control relay group FCR.

Relay 481, upon operating, at its contacts 496 applies ground potential to the holding conductor 486 and over an associated branch conductor 4861. The ground potential on the branch conductor extends via armature 4862 and its back contact, conductor 489, the break contacts of relay 466, and the winding of group marking relay 467 to battery. The relay 481, at its contacts 465, opens a point in the operating circuit of rotary magnet 125 of the finder, and at contacts 464 completes the initial operating circuit of vertical magnet 126. This circuit extends from ground supplied through contacts 48 of interrupter relay 473, the armature 493 and its resting contact, contacts 464, conductor 408, contacts 171, and the winding of vertical magnet 126 to battery. The vertical magnet 126 accordingly operates, and in the well known manner, moves the wipers 147, 149, 151, 159, and 161 of the finder up one step opposite the first level of the associated bank of contacts in which the calling lines terminate. Near the end of the armature stroke 75 of the vertical magnet 126 it applies ground

through its associated contacts to the conductor 127 and via contacts 112 and conductor 405 to the upper winding of interrupter relay 473 and battery. The relay 473 accordingly operates, and completes a locking circuit for itself including 5 its lower winding, its contacts 49, armature 47 and its resting contact, resting contact and armature 41, and the grounded conductor 4861. The relay 473 also completes a circuit for operating relay 475 by applying ground from conductor 486 via 10 armature 492 and its front contact, through the resting contact and armature 46 of relay 474, the upper winding of relay 475, the armature 45 and its resting contact, and the resistance to battery. Relay 473 finally at its contacts 48 opens 15 the circuit of vertical magnet 126, which, in turn, removes ground potential from conductor 127 and from the initial operating circuit of relay 473.

The relay 475, upon operating, at its contacts 20 43 prepares an operating circuit for relay 474, and at its armature 41 interrupts the locking circuit of relay 473. The relay 475 also at its armature 41 breaks the traced locking circuit of interrupter relay 473. This latter relay accordingly restores to normal. Relay 467, which it will be recalled had its circuit completed upon operation of relay 481, at its break contacts opens a point in the locking circuit of relay 471, at its outer upper make contacts closes the obvious 30 operating circuit of relay 486, at its inner upper make contacts complete a locking circuit for itself extending through the upper break contacts of relays 468, 469, 470, 471, to the grounded conductor 486. The relay 467 also, at its inner lower 35 make contacts, prepares a point in the operating circuit of relay 468, and at the remainder of its contacts closes points in the first and seventh group control circuits of each 100 line group, but which are ineffective so far as the present operation is concerned. Relay 466, upon operating, at its upper contacts completes a locking circuit for itself, and at its lower contacts breaks the initial circuit of 467.

The relay 473, upon restoring, completes an 45 operating circuit for relay 474, from ground on conductor 486 applied through armature 492 and its resting contact, through contacts 44 of relay 475 and through the lower winding of relay 474 to battery. The relay 474, upon operating, at 50 its contacts 44 completes a locking circuit for itself excluding the armature 492, at its armature 47 breaks a second point in the traced holding circuit of relay 473, at its armatures 45 and 46 interrupts the operating circuit of relay 475, and 55 at the front contacts of these armatures connects the upper winding of this relay in series with the upper winding of relay 474. Finally, the relay 474, at armature 4862 removes ground from the initial operating circuit of relay 467 and at its 60 front contact applies ground to conductor 488, through the inner lower make contacts of relay 467 and the winding of relay 468 to battery. The relay 468 accordingly operates and at its break contacts interrupts the previously traced locking 65 circuit of relay 467 which accordingly restores. The relay 468 also, at its inner upper make contacts completes a locking circuit for itself similar to the one previously traced for relay 467, at its inner lower make contacts prepares an operating 70 circuit for relay 469, and at the remainder of its make contacts closes points in the second and eighth group control circuits of the first and second hundred groups, not involved in the present connection.

The relay 473, upon deenergizing, also, at its contacts 48 reestablishes the operating circuit of the vertical magnet 126. This magnet accordingly again energizes, elevating the associated 5 wipers a second step and again grounding conductor 127 and thus effecting the energization of interrupter relay 473 a second time. Relay 473, upon operating, now connects ground potential on conductor 486 to the upper terminal of the upper winding of relay 475 via armature 482 and its front contact, the front contact and armature 48 through the upper winding of relay 475, the armature and front contact 46 of relay 474, and the upper winding of this latter relay to battery. 10 Current flow through the upper winding of relay 475 in the direction traced is effective to knock down the armatures of this relay.

The relay 475, upon restoring, at its contacts 48 opens the initial operating circuit of relay 474, 20 and at its front contact and armature 41 completes a locking circuit for relay 473. The relay 475 also, at its armature 41 opens the locking circuit of interrupter relay 473. Relay 473 now restores and at its armature 482 interrupts the circuit of relay 474. The relay 474 accordingly restores to again prepare points in the operating and locking circuits of relays 475 and 473, and at its armature 4862 completes the obvious operating circuit of relay 469. The relay 469, upon operating, at its inner upper make contacts completes a locking circuit for itself including the break contacts of relays 470 and 471 and the grounded conductor 486, and at its break contacts 25 interrupts the circuit of relay 468, permitting it to restore. The relay 469, at the remainder of its make contacts closes points in group control circuits ineffective at this time. The relay 473 also, at its contacts 48 transmits a third impulse to the vertical magnet 126.

40 The vertical magnet 126 accordingly elevates the finder wipers opposite the third level of its associated bank contacts and completes the circuit of interrupter relay 473 a third time. This relay, upon operating, at armature 492 and its front contact again completes the initially traced operating circuit of relay 475, and at its contacts 49 again completes a locking circuit for itself. The relay 475 this time, upon operating, at contacts 43 again prepares an operating circuit for 45 relay 474, and at its armature 41 closes a point in the previously traced locking circuit of relay 473.

Upon the subsequent restoration of relay 473 relay 474 again operates over the previously traced 55 circuit and again prepares a circuit in the reverse direction through the winding of relay 475, which circuit is again completed upon the subsequent operation of relay 473 following the fourth energization of the vertical magnet 126. The relay 474 also upon its energization at its armature 4862 again applies ground to conductor 488 and this time through the inner lower make contacts of relay 468 and winding of relay 470 to battery. This latter relay, upon operating, at its break contacts 60 interrupts the locking circuit of relay 468 permitting it to restore, at its upper make contacts completes its own locking circuit, at its inner lower make contacts prepares an operating circuit for relay 471, and at the remainder of its contacts closes points in group control circuits not effective at this time. Upon a subsequent deenergization of relay 474 under control of interrupter relay 473, the relay 471 becomes operated. This relay at its inner upper make contacts completes a locking circuit for itself including the

upper break contacts of relay 467 and the grounded conductor 488, at its inner upper break contacts interrupts the locking circuit of relay 470 which accordingly restores, and at its uppermost break contacts opens one of two multiple paths 5 in the locking circuit of relay 466. The relay 471 also, at its inner lower make contacts prepares an operating circuit for relay 472, and at the remainder of its contacts closes points in group control circuits not effective at this time. 10

Upon the subsequently transmitted impulse to conductor 488 via armature 4862 relay 472 operates. This relay, at its inner upper make contacts, completes a locking circuit for itself including the grounded conductor 486, and at its 15 upper break contacts interrupts the locking circuit of relay 466. This latter relay accordingly restores, and at its lower contacts again prepares the operating circuit for relay 467. Relay 472 also, at its lower break contacts, opens its own 20 initial operating circuit, and at its armatures 487 and 488 transfers conductors 488 and 409 from connection with contacts of the group marking relays associated with start conductors of the first hundred groups of lines, terminating in the 25 first five levels of the finder, into connection with contacts associated with the start conductors of the second hundred group of lines, terminating in the upper five levels of the finder bank. Upon the next deenergization of relay 474 ground potential is again applied to the conductor 488 and via the break contacts of relay 466 to the winding of relay 467 and battery. The relay 467, upon operating, at its break contacts interrupts the locking circuit of relay 471 and this relay accordingly restores. The relay 467, at its upper make contacts again closes the operating circuit of relay 468, at its inner upper make contacts completes a locking circuit for itself as previously traced, and at its inner lower make contacts again prepares an operating circuit for relay 468. Relay 468 operates as previously and again 30 interrupts the initial circuit of relay 467 which restores. 35

Upon the subsequent operation of relay 474 45 relay 468 becomes energized over the previously traced circuit and in addition to preparing a circuit for relay 468 again effects circuit changes previously effected by it. Upon the subsequent restoration of relay 474 ground is supplied via the armature 4862 and its back contact to the relay 468 over the previously traced circuit. The relay 468, upon operating, in addition to effecting the circuit changes effected by its operation the first time, at its contacts 459 extends ground, on start conductor 410, via the conductor 481, the front contact and armature 498, conductor 490, contact and armature 4004 and the lower winding of change-over relay 482 to battery. This ground potential also extends by way of contacts 4005, 50 conductor 488, contacts 161 of connecting relay 166, and through the lower winding of wiper switching relay 174 to battery. The wiper switching relay 174, upon operating, at contacts 163 completes a locking circuit for itself through its upper winding and the contacts 164 of relay 166, at its contacts 162 interrupts a point in a circuit employed only when the calling subscriber is one of the first hundred group and has his line equipped with a paystation, and at armatures 163, 164, and 165 transfers the talking and test conductors of the link from connection with wipers 147, 148, 151, having access to calling lines in the first hundred group, into connection 55 60 65 70 75

with wipers 157, 159 and 161, having access to subscribers' lines of the second hundred group.

- The change-over relay 482, upon operating, at its contacts 495 interrupts the circuit of relay 481 and at contacts 494 completes a locking circuit for itself including its upper winding, conductor 406 and the front contact and grounded armature 169 of relay 165, and at its armature 493 interrupts a point in the operating circuit of the vertical magnet 126 and prepares a point in the operating circuit of rotary magnet 125. An instant later the relay 481 restores and at its contacts 496, removes ground potential from the holding conductor 486 thereby bringing about the deenergization of any operated ones of the group marking relays GMR and of either of the relays 474 or 475 which may happen to be operated at this time, and at contacts 465 completes the operating circuit of rotary magnet 125. This circuit extends from ground supplied through the contacts 48 of relay 473, armature 493 and its front contact, contacts 465, conductor 407, contacts 173 of relay 165, contacts 180 of test relay 175, and the winding of the rotary magnet 125 to battery. The rotary magnet 125, upon operating, rotates the associated finder wipers into engagement with their first set of bank contacts in the level in which the calling line terminates, in the present example the ninth. The rotary magnet near the end of its operating stroke applies ground potential to conductor 127 as did the vertical magnet 126. The interrupter relay 473 of the allotter accordingly becomes energized and at its interrupter contacts 48 opens the circuit of the rotary magnet. Since the conductor 486 is no longer grounded, owing to the deenergized condition of change-over relay 481, the interrupter relay 473 no longer exerts any influence over the group marking relays or over the finder control relays 473, 373, or 475. The rotary magnet 125, upon restoring, interrupts the operating circuit of relay 473 and this latter relay accordingly restores to again establish the operating circuit of the rotary magnet. It will be obvious, therefore, that the rotary magnet 125 and the finder control relay 473 operate alternately, and that the wipers of the finder are in this manner rotated over the selected group of bank contacts until contacts of the calling line, or in case the calling line is not found until the last contacts of the contact bank are encountered.

In order to prevent the finder of some link from continuously hunting should a call be initiated from a line having an open test contact the following circuits are provided: Each finder is provided with an eleventh rotary bank contact 180 in each of its levels. The ten revertive control relays 141 to the lines of a level have their upper windings connected in series. The winding of the last relay is terminated to battery and the winding of the first relay is terminated on the eleventh step test contact 180.

If, for instance, line 5951 has an open test lead, and the line is taken for use or becomes short circuited, a finder will be started to hunt for this line. Due to the fact that the test contact is open the finder will continue hunting in a rotary direction until it reaches the eleventh step test contact 180. At this point the test wiper will encounter battery in series with the windings of all of the relays 141 of such level and they will operate. As soon as the relay 141 of line 5951, at its armature 143 closes its make contact it will immediately lock itself from ground supplied through the contacts 134 of the operated line re-

lay 131. The relay 141, of the line calling, will at its armature 143 also open up the start conductor 410 and thereby prevent this calling line from starting another finder while the receiver remains off its hook.

We will now return to a consideration of the operations which follow the finder test wiper encountering the test contact of a calling line having calling potential thereon. When this occurs an operating circuit is completed including the cut-off relay 135 of the subscriber's line equipment and the upper winding of the test relay 175 of the link circuit. This circuit extends from the ground supplied through contacts 124 of the relay 165, the upper winding of test relay 175, conductors 199 and 106, armature 155 and its front contact, the test wiper 161, test contact 160, the contacts 132 and 142 and the winding of relay 135 to battery, and via a second branch including the contacts 139 of relay 135 and resistance R1 to 20 battery. The relay 135, upon operating, at its contacts 139 disconnects the resistance R1 and the associated battery from the traced operating circuit of relay 175, at its armature 140 opens a point in the permanent alarm circuit which will 25 be described later, at the front contact of this armature completes a circuit through the lower winding of slow release relay 141, at contacts 138 closes a holding circuit for itself independent of contacts 142, and at contacts 136 and 137 disconnects the line relay 131 from in bridge of the line. The line relay 131, upon restoring, at its armature 133 disconnects direct ground from conductor 1 at its working contact and at its resting contact substitutes the ground now supplied through the working contact and armature 124 of relay 165, the contacts 178 of test relay 175, conductors 199 and 106, armature 155 and its working contact, wiper 161, the associated bank contact 160, the contacts 138, and the contact and armature 133, so as to maintain conductor 1 grounded to busy the line at its called terminal. The opening of contacts 132 of the line relay 131 is without effect owing to the establishment of the substitute circuit for relay 135 30 including its contacts 138. The relay 141, upon operating, at its contacts 144 closes a point in an alarm circuit, at armature 143 disconnects ground from the start conductor 410 and prepares a point in its own locking circuit. The relay 131, 35 however, at its contacts 134 prevents the completion of this latter circuit at this time and removes ground from the start conductor 410.

The relay 175, upon operating, at its contacts 180 interrupts the circuit of rotary magnet 125 40 and thereby prevents further movement of the finder wipers, at its contacts 178 shunts out its upper winding so that the ground supplied through the contacts 124 and 165 will be effective to replace that formerly derived through the front contact and armature 133 of line relay 131, as previously explained. The relay 175, at contacts 176 and 177 connects the talking conductors of the calling line through to conductors 192 and 103 of the link, and at its contacts 179, 45 completes an operating circuit for the cut-through relay 423 of the allotter control relay group ACR. The circuit of relay 423 includes contacts 168 of relay 165 and the cut-through conductor 404. The cut-through relay 423, upon 50 operating, at its contacts 424 prepares the locking circuit for relay 427, at contacts 425 opens a point in one of the locking circuits of relay 418, which is ineffective at this time, at contacts 426 places a shunt circuit about the lower winding of 55

relay 438 to prevent its premature operation as will be later explained.

It will be recalled that upon operation of relay 175 the calling line was extended into connection with the talking conductors 102 and 103 of the link, at contacts 176 and 177. When this occurs an operating circuit is completed for the link line relay 245. This circuit extends from ground through the relay 245 through the contacts controlled by armature 251, conductor 202, through contacts controlled by armature 341, the conductor 102, contacts 176, armature 153 and its front contact, wiper 157 and its associated bank contact 158 to the line conductor 128, through the substation equipment, line conductor 129, the bank contact 158 and the associated wiper 159, the front contact and armature 154, contacts 177, conductor 103, through contacts controlled by armature 340, conductor 204, contacts controlled by armature 252, conductor 208, and the lower winding of relay 349 to battery and over a second branch in multiple with relay 349 and extending via contacts 258 and resistance R21 to battery. The resistance R21 is low compared to that of relay 349 and therefore 349 does not operate over the traced circuit so long as resistance R21 is included therein. The relay 245, upon operating, at its upper contacts closes a point in a circuit effective an instant later by operation of armature 247, and at its lower contacts completes an obvious operating circuit for the relay 246. The relay 246, upon operating, at its contacts 248 applies ground potential to conductor 227 via the resistance R22, but which is ineffective at this time, and at armature 247 removes ground potential from conductor 113 and at the front contact of this armature applies ground potential over conductor 114 to and through the winding of slow release relay 194 to battery. The relay 194, upon operating, completes an obvious operating circuit for the relay 190. The latter relay, upon operating, at its armature 191 separates conductors 105 and 106 and connects ground potential to the conductor 106 to replace that being applied to it by the contacts 124 of the connecting relay 165; at contacts 193 applies ground potential, via the springs controlled by armature 183, to conductor 119 and to the lower winding of the test relay 175 in substitution for the ground being applied by the contacts 166 of the connecting relay 165, and at contacts 192 completes an obvious operating circuit for the slow release relay 195. The latter relay, upon operating, at its contacts 198 closes a point in the operating circuit of time release relay 181, at its contacts 196 closes a point in a circuit including the operating magnet 320 of the class and code selecting switch CC and of the series relay 263 in multiple, which circuits will be traced subsequently. The relay 195 also, at its uppermost contacts, connects dial tone to talking conductor 103 by way of conductor 101, contacts 280, 287, the back contact and armature 294, conductor 201, contacts 367, condensers C31 and C32, conductor 204, and the contacts controlled by armature 340 to conductor 103. The relay 195 also, at its contacts 197 completes a circuit extending over conductor 116 and through the lower winding of relay 235 to battery. The relay 235, upon operating, at its contacts 238 completes a locking circuit for itself including the conductors 115, 199 and the previously grounded hold conductor 106; at contacts, controlled by its armature 239, removes direct ground from the winding of relay 246 and substitutes therefor ground potential supplied

through resistance R22 and contacts 248 of relay 246. The relay 235 also, at its contacts 236 supplies ground potential to conductor 107 in order to maintain the wiper switching relay 174 energized independently of contacts 164 of the connecting relay 165, at its contacts 243 applies ground to conductor 223 for a purpose having utility only when outgoing trunk calls are being set up, and at its armature 241 removes ground potential from the class and code switch release conductor 224 and connects this conductor to the conductor terminating at armature 289 of the relay 284. The relay 235, furthermore, at contacts 240 applies ground potential to conductor 117, through contacts 189, time start conductor 709, contacts 757 of relay 756 of the time cut-off relay group TCO and through the winding of solenoid 750 of this group to battery, and via a branch conductor 709', the armature and back contact of relay TCI, to the winding of slow release relay 751 and battery. Finally, the relay 235 at its contacts 242 applies ground potential to the guard conductor 401, through contacts 443 of the link selecting relay 439, the upper winding of relay 446 of this group, the conductor 454, contacts 432 of relay 431, and through the upper winding of relay 427 to battery.

The relay 427, upon operating, at its contacts 430 completes a locking circuit for itself including its lower winding and contacts 424 of the cut-through relay, at its contacts 429 interrupts the previously traced circuit of the connecting relay 165 in the link circuit, and at its contacts 428 places low resistance R48 in multiple with its upper winding, thereby increasing the current flow over the traced circuit sufficiently to enable the operation of the link selecting relay 446, and the consequent association of the next idle link with the allotter.

The relay 165, upon restoring, at its armature 164 opens the initial locking circuit of relay 174, but without effect at this time since ground is now being supplied to the locking winding of this relay via contacts 236 of relay 235, as previously explained; and at contacts 166 removes ground potential at this point from the winding of test relay 175, but without effect because of the previously substituted ground potential through contacts 193 of relay 190. The relay 165, also, at its contacts 169 interrupts the circuit of change-over relay 482 of the finder control group FCR, which accordingly restores, at its contacts 170 removes ground potential from one of the twelve multiples extending by way of conductor 403 to the all link busy relay 431, and at its contacts 168 interrupts the previously traced circuit of the cut-through relay 423. The relay 165 also at its contacts 173, 171, and 172, disconnects the vertical and rotary magnets and the control conductor 127 from association with the allotter.

The link selecting relay 446, upon operating, at its lowermost break contacts interrupts the locking circuit of relay 439 causing it to restore; at its inner lower make contacts completes a locking circuit for itself including the lowermost break contacts of the third link selecting relay (not shown), thereby maintaining the slow release relay 435 energized. The relay 446, at its contacts 443', prepares an operating circuit for the next link selecting relay of this chain, at its contacts 442' closes a point in the guard circuit of the associated link, at its contacts 440' connects the start conductor of such link to the common conductor 455, and at break contacts 441' opens a point in the guard circuit of the next link of the 75

series. The relay 439, upon restoring at contacts 440 disconnects the start conductor 402 of link 1 from conductor 455, at its contacts 441 closes another point in the guard circuit of link 3, at 5 its contacts 442 opens a point in the guard circuit of link 1, at contacts 443 opens the initial operating circuit of relay 446 and 427, at its contacts 444 interrupts its own locking circuit at a second point, and at its contacts 445 prepares 10 a locking circuit for the relay 447.

Upon the restoration of the cut-through relay 423 as a result of this circuit having been opened at contacts 168 of relay 165; the relay 423 at its contacts 424 opens the locking circuit of relay 15 427, permitting that relay to restore, and at its contacts 425 again prepares a point in the locking circuit for relay 418 which is independent of the all link busy relay 431, and at its contacts 426 opens the shunt previously placed about the 20 marginal relay 438. The relay 423 also, at its lowermost contacts, opens the locking circuit of relay 4001 which accordingly restores and removes ground from the start lead 4008, providing no other lines have in the meantime initiated a 25 call. The relay 427, upon restoring, at its contacts 429 again prepares the conductor 455 for receipt of ground potential when the relay 418 becomes energized consequent to the initiation of another call.

30 The removal of the shunt circuit from about the lower winding of relay 438 by relay 423 is without effect so far as the operation of relay 438 is concerned, unless due to some abnormal condition, current is supplied to it from more than one of the link selecting relays, such as 439. Should this occur, for example, as a result of a maintenance man working on the contacts of these relays, the relay 438 will become energized and at its lower contacts interrupt the locking 35 circuit of any operated ones of the link selecting relays, and at its upper contacts will become locked energized through the contacts 436 of the slow release relay 435. Since these locking circuits both include the slow release relay 435 the latter relay after a slight delay will deenergize, and at its contacts 437 establish an operating 40 circuit including the conductor 453, the upper winding of relay 439, the contacts 432 of all link busy relay 431 and the upper winding of relay 45 45 427 to battery. The relay 427 will accordingly operate followed by the operation of relay 329 to again preselect a link circuit. The slow release relay 435 upon restoring also breaks the locking circuit of the marginal relay 438 and accordingly the relay 439 will become locked 50 up through the break contacts of the relay 438 and the winding of the slow release relay 435. The latter relay will accordingly again become energized and in so doing at its contacts 437 will 55 again interrupt the initial operating circuit of the relay 439.

In case all of the link circuits become busy 60 all of the circuits such as described for the all link busy relay 431 will be interrupted and this relay will accordingly restore. This relay, upon restoring, at its contacts 460 interrupts the operating circuit of start relay 418, so as to prevent relay 418 being operated when a subscriber initiates a call at a time when no idle links are available. The relay 431, at its contacts 432, opens 65 a point in the operating circuit of relay 439 which might otherwise be completed following the operation of the last link selecting relay 447 of the chain, even though the link circuit associated 70 with the relay 447 is already in use, at its contacts 75

433 opens the controlling path extending from the timing relays 411, 413, and 414, and at its armature 434 removes ground potential from the common locking circuit of the link selecting relays and from the operating circuit of relay 435, and applies this ground via the contacts 415 and the timing relay 411 to battery. 5

As soon as one of the links becomes idle the all link busy relay 431 again becomes energized to again establish the operating circuit of relays 10 418 and 427 and the link selecting relay of the then idle link. These relays accordingly operate as before followed by the operation of relay 435 which again is included in the locking circuit of such link selecting relay, after which the circuits will be in the condition in which they are shown, providing the link which became idle is the one associated with relay 439. 15

When the calling subscriber hears dial tone he proceeds to operate his calling device in the usual manner to transmit the digits of the called number. If the first digit transmitted simply comprises a preliminary impulse, relay 245 at its lower contacts interrupts the circuit of repeating relay 246 only once, and the latter relay, 25 in turn, at its armature 247 and its back contact transmits one impulse out over conductor 113, through contacts 196, conductor 112, to the winding of slow release relay 263 and battery, by way of armature 259 and its back contact and 30 contacts 264 to the upper winding of relay 270 to battery, and also by way of armature 278 and its back contact, the lowermost armature of relay 296 and its back contact, conductor 226, to the winding of rotary magnet 320 of the switch 35 CC to battery. The relay 246 also at its contacts 248 opens its own locking circuit. The magnet 320, however, near the end of its armature stroke applies ground potential direct to conductor 227, thereby enabling relay 246 to operate from this 40 direct ground as soon as the lower contacts of line relay 245 again close.

The relay 263, upon operating, at its contacts 264 closes an obvious circuit through the lower winding of relay 270. The circuit traced through the upper winding of relay 270 including its own break contacts 254 assists the relay 263 in the quick operation of relay 270. The contacts 254 of this relay are arranged to break after all other contacts of the relay have been actuated. 50

Upon the termination of the transmission of the first series of impulses, in the present example simply a preliminary impulse, the line relay 245 remains energized as does also the pulsing relay 246. The prolonged removal of ground potential from the pulsing circuit permits the deenergization of slow release relay 263, which has remained operated throughout the impulse series. This relay at contacts 264 interrupts the circuit of relay 270, permitting that relay to 60 also restore to normal. With the wiper 318 of switch CC in engagement with its first contact; the relay 270, upon restoring, at its armature 274 and its back contact completes a circuit including the release magnet 319 of the switch CC 65 causing it to restore. This circuit extends from battery through the magnet 319, the off normal springs ON3, closed upon the initial movement of the wipers of switch CC off normal, conductor 224, first bank contact and wiper 318, conductor 225, contacts 288, 282, and 274, resting contact and off-normal spring ON21, and contacts 291 to the grounded conductor 217. 70

If the first digit transmitted is two the relay 270, upon restoring, at its armature 274 and its 75

back contact now completes an operating circuit for relay 277. This circuit extends from the grounded hold conductor 107, grounded by armature 236 of relay 235, the contacts 331 of relay 5 336, conductor 217, contacts 281, off normal spring ON21 and its resting contact, back contact and armature 274, contacts 282, 288, conductor 225, the wiper 318 of the class and code switch CC, and its second bank contact, and the conductor 10 218 and winding of relay 277 to battery. The relay 277, upon operating, at its contacts 281 completes the circuit of the release magnet 319 of the class and code switch. This circuit extends from ground on the conductor 107 and its branch 15 2071 through contacts 281, the back contact and armature 289, the front contact and armature 241, conductor 224, the off normal contacts ON3, closed upon the initial movement of the wipers of switch CC, and the magnet 319 to battery. The 20 switch CC accordingly restores, and upon reaching its normal position, again opens its contacts ON3. The relay 277 at its contacts 283 completes a locking circuit for itself independent of the switch CC via contacts 269 and 281 to the 25 grounded conductor 217, at its contacts 282 opens a point in its initial operating circuit; at its armature 278 transfers the impulsing circuit from association with the magnet 320 of switch CC into association with the operating circuit of vertical 30 magnet 234 of the connector switch of the link, via the resting contact and armature 283 of relay 284; and at its contacts 280, interrupts the dial tone circuit.

The operation of only the relay 277 determines 35 that the link will select a line in the first hundred group and that the code signal transmitted out over the called line will comprise one of the first ten codes and will be transmitted over the ring conductor 302 of the link. If the first digit 40 dialled is three, the ground potential supplied over the wiper 318 and its third bank contact, following the deenergization of relay 270 at the conclusion of the impulse series, extends through the lower winding of relay 332 to battery. The 45 relay 332, upon operating; at contacts 327 and 328 transposes the generator and ground connections of the link, and thereby determines that the called line is one of the first hundred group and that it will be signalled by one of the first ten 50 codes transmitted over the tip conductor 303 of the link. The relay 332 also, at contacts 329 completes a circuit for relay 277, from battery through the winding of this relay, conductor 218, contacts 329, conductor 219, contacts 261 and over the previously traced circuit to ground, and at its 55 contacts 331 completes a locking circuit for itself including the contacts 356 and the grounded conductor 217.

If the first digit transmitted is four, the wiper 60 318 will be in engagement with its fourth bank contact and will complete a circuit through the windings of relay 326. The relay 326, upon operating, at contacts 329 completes the circuit of relay 277 as did relay 323, at contacts 331 completes a locking circuit for itself, and at its lowermost 65 armature prepares the link for signalling a line in the first hundred group with one of the second ten codes over the ring conductor 302.

If the first digit transmitted is five, the wiper 70 318 completes a circuit through the lower winding of wiper switching relay 368. The relay 368, at its armatures 372, 373 and 374 determines that the line called will be one of the second hundred, at its contacts 369 completes a locking circuit for itself, and at its contacts 329 completes the cir- 75

cuit of relay 277. Since the relay 326 is not operated it is determined that the selected line in the second hundred group will be signalled over the ring conductor 302 by one of the first ten codes. 5

If the first digit transmitted is six, ground on the wiper 318 completes the circuit through the upper windings of relays 368 and 332 in series. Obviously, relay 277 also operates. The relay 368 again determines that the called line will be one 10 of the second hundred, while the relay 332 again determines that ringing will occur over the tip conductor 303 of the link.

The relay 270, upon restoring, following the transmission of the first digit, in all instances, 15 completes the previously traced circuit through the release magnet 319, causing the switch CC to restore to normal.

If the first digit is greater than seven the link is prepared for a call to the toll operator, as will 20 be explained subsequently.

In the connection at present being described, the first digit transmitted is two, accordingly, the link is prepared as previously described to transmit signalling current of one of the first ten codes 25 over the ring conductor 302 of the link.

Upon the transmission of the second digit, in the present example comprising six impulses, the relays 245 and 246 operate as before, as do relays 263 and 270. The vertical magnet 234 of the 30 connector now operates in multiple with relay 263 and elevates its wipers opposite the second level of their bank contacts. The off-normal springs ON21, 22 and 23 operate on the first movement of the wiper shaft; at ON23 place a 35 multiple ground on the guard conductor 401, from the armature 169 and its resting contact over conductors 121 and 122, to hold the link busy until the connector switch returns to normal; and at contacts ON21 interrupt the initial circuit of 40 relay 277. The vertical magnet 234 supplies ground potential, upon each operation, to the conductor 227 to supply operating ground to the relay 246 in the same manner as did the magnet 320 of the class and code switch CC. 45

At the termination of the transmission of the second digit of the called number the relays 263 and 270 restore as before. The relay 270 now, at its armature 275 and its back contact, completes an operating circuit for the relay 284. This circuit extends from ground on conductor 217, through contacts 291, off normal spring ON21 and its working contact, armature 275 and its resting contact, and the winding of relay 284 to battery. The relay 284, upon operating, at contacts 287 opens a second point in the dial tone circuit, at its contacts 286 closes a point in the circuit of test relay 228, at its armature 285 transfers the pulsing circuit from the vertical magnet 234 of the connector switch to the rotary 60 magnet 233 thereof by way of the lower winding of relay 266, at its contacts 288 opens another point in the initial operating circuit of relay 277, at its inner lower make contacts completes a locking circuit for itself including contacts 291 and 65 292, the grounded conductor 217, and at its armature 289 opens a second point in the previously traced circuit of release magnet 319 of the switch CC and at the front contact of this armature prepares an operating circuit for the relay 253. 70

Upon transmission of the third digit, comprising a series of four impulses, the relays 263 and 270 operate as before. The impulse circuit to the rotary magnet 233, as previously explained includes the armature 285 and its working contact 75

and the lower winding of relay 266. The rotary magnet 233 at its front contact applies ground from contacts 243 through conductor 233 to the conductor 227 to control the circuit of relay 246. In the same manner that it was previously controlled by magnets 320 and 234. The relay 266, upon operating, at its contacts 267 completes a locking circuit for itself including its upper winding and the contacts 237 of relay 235, at its contacts 268 opens a point in the operating circuit of relay 290, and at contacts 269 interrupts the formerly traced operating circuit of relay 277. The relay 277, however, remains energized until after relay 270 deenergizes following the transmission of the third digit of the called number, by ground supplied to it from conductor 116 through contacts 265, 2901, and 283.

Following the termination of the transmission of the third impulse series, the relay 263 at its contacts 265 interrupts the circuit of relay 277 and the latter relay accordingly restores. The relay 277, upon restoring, at its armature 278 interrupts the impulsive circuit to the rotary magnet 233 and at its back contact, reestablishes the impulsive circuit extending to the operating magnet 320 of the switch CC.

Ringing code selection

Upon the transmission of the fourth or final digit of the called number relays 263 and 270 operate as before, while the five impulses transmitted in the present example, cause the magnet 320 of switch CC to position its wipers in engagement with their fifth bank contacts to, by means of the position of wipers 316 and 317, determine the code to be transmitted to the called line.

Following the transmission of the final impulse of the fourth series, the relay 270, upon restoring, at armature 271 and its resting contact completes an operating circuit for relay 253 which includes its upper winding, the front contact and armature 289 and battery supplied over the previously traced release circuit including the magnet 319 of switch CC. Owing to the high resistance of relay 253 compared to that of the magnet 319 only 253 operates over this circuit. The relay 253, upon operating, at contacts 256 closes a locking circuit for itself including its lower winding and the grounded conductor 1071. The relay 253 at its contacts 255 places a shunt about the upper or holding winding of relay 266, causing it to restore; at contacts 259 opens a point in the impulsive circuit to prevent further operation of the class 55 and code switch when the circuit of relay 246 is again interrupted; at its contacts 258 removes the resistance R21 and battery from in shunt of relay 349, thus allowing this relay to operate over the calling line loop; and at its contacts 260 prepares a locking circuit for relay 349. The relay 349, upon operating, at its inner upper contacts completes the prepared locking circuit for itself and which includes contacts 3471, conductor 2161 and the contacts 260 of relay 253. The relay 349 also, at its upper armature opens a point in the operating circuit of relay 336 and closes a point in the operating circuit of relay 347. The relay 353 in addition to producing the foregoing circuit changes, resulting in the operation of relay 349, at its contacts 257 completes an operating circuit for the test relay 228 providing the called line is idle. This circuit extends from battery through the winding of the cut-off relay 393 of the called line, the break contacts of the line relay 397 of the called line, conductors 389, test

contact 386, wiper 385, the contact and armature 372, test conductor 210, contacts 279, the armature 272 and its resting contact, contacts 257, armature 34 and its resting contact, contacts 288, and through the upper winding of the test relay 228 to ground. If the called line is busy while the impulses are being transmitted to the code switch the test wiper 285 will encounter ground potential and in so doing cause the busy relay 239 to operate, then at the end of the impulse series if the line has become idle the relay 228 will operate over a momentarily established circuit including contacts 286, back contact and armature 293 front contact and armature 34 and over the previously traced circuit to battery. Under these circumstances, the relay 228 at contacts 24 breaks the circuit of relay 230, permitting it to restore. The relay 253, upon operating, also at contacts 260 completes the circuit of slow to operate relay 290 via contacts 268 of relay 266. Relay 290 operates and at contacts 292 closes a point in the circuit of pick-up relay 258. The relay 290 also, at contacts 291 opens the locking circuit of relay 284, which now restores.

The relay 228, upon operating; at its contacts 21 completes a circuit for the generator start relay 620 by way of conductor 221, contacts 357, conductor 315, and contacts 639; at its contacts 23 applies ground potential to conductor 219 and through the armature 372 and its resting contact, wiper 385 to the test contact 386 of the called line to maintain the same busy to other calling subscribers, and at its contacts 24 opens a point in the operating circuit of the busy relay 230.

The cut-off relay 393 of the called line, upon operating, at its contacts 394 and 395 removes the associated line relay from in bridge of the line, at its inner upper break contacts removes battery and resistance R35 from in multiple with the relay 393, at its contacts 396 extends the ground potential on conductor 389 via the break contacts of the line relay 397 into connection with the finder multiple test conductor 398, and at its armature 399 opens a point in the alarm circuit to be described later and completes an operating circuit through the lower winding of relay 341'. The operation of this latter relay is without effect at this time.

Ringing.

At the beginning of the first ringing code cycle following the energization of relay 228 a ground impulse is transmitted to the pick-up conductor PU in a manner which will subsequently be described. When this occurs a circuit for the pick-up relay 358 is completed through the break contacts and upper winding of this relay, contacts 349, conductor 215, back contact and armature 297, contacts 292, and through the front contact and armature 22 of relay 228 to battery. The relay 358 at its contacts 359 completes a locking circuit for itself including its lower winding, contacts 356 and the grounded conductor 217; at contacts 360 connects the lower winding of the ringing relay 343 to the wiper 316 of switch CC; and at contacts 361 connects the upper winding of relay 343 to the wiper 317 of switch CC, via contacts 361' and bank contact and armature 325. The relay 358 also, at contacts 365 and 366, closes points in the ringing circuit, at armature 367 substitutes a ringback tone circuit branch for the dial tone circuit, and at contacts 362, 363 and 364 prepares circuits which will be described later. Ground impulses supplied from the code interrupter, in a manner which will be subse- 75

5 quently described extend via the wipers 316 and 317 and operate the ringing relay 343 as required to produce the desired ringing code. The relay 343, when operated, at its armatures 344 and 345 closes the ringing circuit to the link conductors 302 and 303 to the called line; and at its contacts 346 closes the ringback tone circuit.

10 Since the relay 332 is at normal ground connected generator current from the generator lead 10 GEN. extends through the associated resistance, contacts 323, back contact and armature 328, front contact and armature 345, and contacts 366 to the ring conductor 302 to the ringers and condensers on the ring conductor of the called 15 line to ground in the case of a divided ringing line such as shown or back through the tip conductor 303, contacts 365, armature 344 and its front contact and armatures 327 and 322 and their back contacts to ground in the case of a 20 bridged ringing line.

Had the relay 332 been operated the ringing current on a divided ringing line would have been transmitted to the tip conductor 303 and through the ringers on that conductor of the called line 25 to ground.

In the present example ringing current is applied to conductor 302 through armature 374 and its resting contact, the wiper 381, bank contact 382, conductor 387, through the switchhook contacts of station 2645 and the associated ringer 30 to ground. The relay 343 also at contact 346 connects the generator lead, by way of the front contact and armature 367, condensers C31 and C32, conductor 204, through contacts controlled 35 by armature 340, to conductor 103 to transmit ring-back tone to the calling subscriber.

Immediately preceding the removal of each ground pulse over the combination lead and wiper 316 and for a short interval thereafter, the drain 40 lead DRI is grounded as will hereinafter be explained, to close a circuit through the lower winding of relay 333, which accordingly, operates. The relay 343, upon restoring, at the end of the ringing pulse over the combination or mask conductor, connects the ring lead 302 via armature 335 and its working contact and through the associated resistance to battery, and the tip lead 303 via armature 334 and its working contact and the associated resistance to ground, to discharge the 45 condensers in series with the ringers on the called line. When ground is removed from the drain lead DRI relay 333 restores and transfers the conductors 303 and 302 to the relays 220 and 347, respectively, to prepare the link for cutting off 50 the ring.

When the called party hears his code signal and answers, either during a silent period or between codes a circuit is completed through the subscriber's loop for energizing the ring cut-off relay 347 and back bridge relay 229 as follows: from ground on holding conductor 107, through the winding of ring cut-off relay 347, the front contact and armature of relay 349, contacts 334, 344, 365, talking conductor 303, to and 60 through the called station apparatus and back over conductor 302, contacts 366, armature 345 and its back contact, armature 335 and its back contact, conductor 203, armature 38 and its back contact, and the winding of back bridge relay 229 to battery. The relay 347, upon operating, at its contacts 348 completes a locking circuit for itself, at its contacts 356 interrupts the locking circuit of the pick-up relay 358 permitting it to restore, at contacts 349 opens a point in the pick-up circuit of the pick-up relay 358, to prevent 70

it from reoperating when the pick-up lead PU is again grounded; at contacts 357 interrupts the generator start circuit thereby bringing about the deenergization of generator start relay 620, if no other link is maintaining it operated at this time; 5 at its contacts 350 opens a point in the locking circuit of relay 230, at its contacts 341 opens the locking circuit of relay 349 which, however, remains energized over the calling line loop; and at its contacts 353 and 354 connects the back 10 bridge relays 186 and 229 in bridge of the talking conductors 302 and 303 extending to the called line. The back-bridge relay 229 is connected by way of the resting contact and armature 38, conductor 203, and contacts 354 to the conductor 302, 15 while the relay 186 is connected by way of conductor 104 and contacts 353 directly to the conductor 303.

The relay 186, upon operating, at its contacts 187 closes a point in the circuit of reversing relay 20 250 completed only when the call is extended from a paystation line, at contacts 188 disconnects the time pulse lead 707 from the lower winding of relay 181, and at contacts 189 removes ground from the time start lead 709 to prevent the automatic 25 disconnection of the link. The relay 229, upon operating, at its contacts closes points in circuits employed only during the establishment of reverting call connections, and which are described 30 hereinafter.

Talking battery is supplied to the calling subscriber through the windings of relays 245 and 349, and to the called subscriber through the windings of relays 186 and 229.

After conversation and in response to the called 35 party replacing his receiver, relays 186 and 229 restore. The restoration of relay 229 is without effect at this time. The relay 186, upon restoring, at its contacts 189 again closes the circuit of the solenoid 750 and of its associated relay 751, so as 40 to start the timing operation; and at contacts 188 connects the relay 181 to the time pulse lead 707 to insure the release of the link should the calling subscriber fail to replace his receiver.

When the calling subscriber replaces his receiver the circuit to line relays 245 and 349 is broken and these relays accordingly restore. The restoration of relay 349 is without effect. The relay 245, however, upon restoring at its lower contacts interrupts the circuit of relay 246 and 50 at its upper contacts interrupts one of the two multiple ground paths to slow release relay 194. The relay 246, upon restoring, at contacts 248 opens a point in its holding circuit, and at armature 247 interrupts the circuit of relay 194 and 55 transmits a pulse of current to the slow release relay 263 in the same manner as when a dialled impulse is being transmitted. The operation of relay 263 at this time, however, is without effect.

Upon the restoration of slow release relay 194, 60 the circuit for the associated slow to release relay 190 is interrupted. This latter relay, upon restoring, at its contacts 192 interrupts the circuit of relay 195; and at its armature 191 removes ground potential from the conductor 106, and accordingly from conductors 199 and 115.

The relay 195, upon restoring, at contacts 196 opens the circuit of relay 263, which now restores, and at contacts 198 disconnects the lower winding of the time release relay 181 from the time 70 pulse lead 707.

The removal of ground potential from conductor 106 is also effective to bring about the deenergization of the cut-off relay 135 of the calling line. The cut-off relay accordingly restores and 75

reestablishes the circuit of the calling line to a normal non-calling condition.

The removal of ground potential from conductor 115, and also from conductor 116 resulting 5 from the opening of contacts 197 of relay 195 effects the interruption of the operating and holding circuits of relay 235. The removal of ground potential from conductor 116 also enables relay 228 to restore.

10 The relay 235, upon restoring, at its contacts 241 applies ground potential to the conductor 224 and over the previously traced circuit to the release magnet 319 of the class and code switch CC causing it to restore in the manner previously described. The relay 235 at its contacts 242 removes ground potential from guard conductor 401 so as to mark the link as being again available for use, and at contacts 240 removes ground potential from the lead 117 extending via contacts 15 189 and time start conductor 709 to the time start solenoid 750 and its associated relay 752 so as to stop this equipment from functioning in view of the fact that release is taking place in the normal manner. The relay 235 also at its contacts 236 20 removes ground potential from the hold conductor 107 thereby interrupting the locking circuit of relays 253, 347, 368 and 174 which accordingly restore; and at its contacts 244 completes a circuit to the release magnet 231 of the connector 25 magnet which may be traced as follows: from ground at the armature 169 and resting contact of relay 165, conductor 121, contacts 244, off-normal spring ON22 and its working contact, and the winding of release magnet 231 to battery. The 30 connector mechanism and its associated wipers accordingly restore to normal in the usual manner. When the off-normal contact spring ON22 encounters its normal contact a circuit is established to the release magnet 130 of the finder 35 mechanism of the link. This circuit extends from ground on conductor 121, through the contacts 244, off-normal spring ON22 and its resting contact, conductor 120, off-normal spring ON12 and its working contact, and the winding 40 of the release magnet 130 to battery. The finder mechanism and its associated set of wipers are accordingly restored to normal position in the well known manner.

Called line busy

50 Having explained the operations which occur when an idle line is called, a description will now be given of the operations which occur when the called line is busy. It will be recalled that during 55 the receipt of the impulses of the third digit the relay 246 repeated impulses over a circuit including the relay 266 and that this relay operated and at its contacts 269 shifted the locking circuit of operated relay 277 from its control 60 to the contacts 265 of relay 263, so that following the transmission of the third series of impulses the relay 263, upon restoring, interrupts the circuit of relay 277. Now, with the called line busy, upon transmission of the fourth series of 65 impulses, the relay 270, upon operating, at its armature 272 and its working contact completes an operating circuit for the busy relay, from ground supplied over the test conductor 210, to contacts 279, the armature 272 and its working 70 contact, contacts 24 of the test relay 228 and through the winding of relay 230 to battery. The relay 230, upon operating, at its contacts 39 applies busy tone by way of the working contact and armature 294 and over the previously traced 75 circuit to the calling line, and at contacts 33

prepares a locking circuit for itself extending from the grounded hold conductor 107 through contacts 350, conductor 209, contacts 33, contacts controlled by armature 272, and contacts 24. The relay 230 also at its other contacts makes circuit 5 changes employed in the course of setting up a reverting call connection which will be described hereinafter. An instant later relay 270 restores and at contacts controlled by armature 272 closes the locking circuit of relay 230 and opens the operating circuit thereof. 10

The calling subscriber, upon hearing the well known busy tone, replaces his receiver and in so doing opens the circuit of the line relays 245 and 349. The restoration of relay 349 is without effect at this time. The relay 245, however, upon restoring, is effective as before to interrupt the circuit of relay 246. This latter relay restores and at armature 247 interrupts the circuit of relay 194 which, accordingly, restores. The relay 194 15 opens the circuit of relay 190. Relay 190, upon restoring, at contacts 193 opens the circuit of relay 175, which restores and frees the line from the link; at its contacts 192 opens the circuit of relay 195 and at its contacts 191 removes ground 20 potential from the test conductor 106 and from the branch conductors 199 and 115, thereby interrupting the locking circuits of relays 235 and 135, which accordingly restore. The relay 235, upon restoring, at contacts 238 removes 25 ground from the hold conductor 107, thereby interrupting the locking circuits of relays 230, 368 and 174 which accordingly restore; and at contacts 244 initiates the operations previously described which bring about the restoration of the 30 switch CC and of the finder and connector wipers of the link.

Pay station connections

Subscribers' lines equipped with paystations 40 are grouped together and have their lines terminating in a particular level of the first hundred group of finder bank contacts. When a finder elevates its wipers opposite such a level it closes its normal post springs NP, and in so doing prepares an operating circuit for the reversing relay 45 250. This circuit extends from ground on the normal post springs NP, through contacts 187 and 162, conductor 111, and the winding of relay 250 to battery. 50

In such a connection, when the called subscriber answers, the back bridge relay 186 at its contacts 187 completes this circuit. The relay 250, accordingly, operates to reverse the normal battery and ground connections with respect to 55 the calling line and to thereby operate the paystation mechanism of the calling station to collect the deposited coin in the usual manner.

Reverting calls

60 A description will now be given of the operations which take place when a subscriber calls another subscriber on his own line. For this purpose it will be assumed that the subscriber at station 5951 desires to communicate with a 65 subscriber at station 5956 and, accordingly, removes his receiver and proceeds to dial the digits of the called station. During the testing stage of the connection, since the called line is also the calling line, the busy relay 230 will be actuated the same as if any other busy line is being called. 70

When the calling subscriber hears the busy tone he will replace his receiver, thereby opening the circuit of the link line relays 245 and 249 per- 75

mitting these relays to restore. The relay 245, upon restoring, at its lower contacts interrupts the circuit of relay 246 and this relay accordingly also restores. These two relays, upon restoring, at their upper armatures remove ground potential from conductor 114 extending to the slow release relay 194. The relay 246, also, at its armature 247 and its resting contacts again connects ground potential to the slow release relay 263. The relay 263 accordingly operates and at its contacts 265 extends ground potential on conductor 116 via front contacts and armatures 2901 and 34, contacts 257, the back contact and armature 272 and contacts 279 to the test conductor 210 now connected via the wiper 379 with the connector normal conductor 1 of the calling line. This ground potential extends through the armature 133 and its resting contact to the winding of cut-off relay 185 and via contacts 188 to the finder test terminal 160. The relay 194, upon restoring, interrupts the circuit of slow release relay 190. The relay 190, upon restoring, at its contacts 192 opens the circuit of slow release relay 195; at contacts 193 opens the circuit of relay 175, which restores; and at its armature 191 and its resting contact now completes an operating circuit for relay 229. This circuit extends from the ground just traced to test contact 160, armature 191 and its resting contact, conductor 105, contacts 36 of busy relay 230, and the winding or relay 229 to battery.

Relay 229, upon operating, at contacts 28 closes the circuit of generator start relay 620; at contacts 28 connects battery supplied through resistance R24, and through the armature 22 and resting contact of test relay 228 to conductor 215, to prepare the pick-up relay 358 for operation under control of the code interrupter in the same manner as when some other line is called; and at its contacts 27 completes a holding circuit for slow release relay 195 before this latter relay has had time to restore consequent to the opening of contacts 192. This holding circuit extends from battery through the winding of relay 195, conductor 109, contacts 27 and 35, conductor 108, to the grounded contacts of armature 183.

It will be observed that since the calling line is one of the second hundred group the wiper switching relay 368 will have been operated following the transmission of the first digit "5" of the called number. This circuit extends from battery through the lower winding of the relay 368, the fifth bank contact and wiper 318 of switch CC, conductor 225, contacts 288 and 282, armature 274 and its resting contact, resting contact and off normal spring ON21, and contacts 291 to the grounded conductor 217. The relay 368, upon operating, at its armatures 372, 373 and 374 connected the connector end of the link with the wipers 375, 377, and 379, having access to the second hundreds group of lines, at its contacts 369 completed a locking circuit for itself, at its contacts 3292 closed a point in a holding circuit for relay 277 which is independent of contacts 291 of the slow to operate relay 290, and at its contacts 371 opened a point in an automatic trunk hunting circuit which will be described hereinafter.

In response to the operation of the generator start relay 620, consequent to the operation of relay 229, the ringing equipment of Fig. 6 and the code interrupter equipment of Fig. 5 operate in substantially the same manner as previously described to transmit a ringing code in accordance

with the code combination selected by the positioning of the switch CC in response to the transmission of the last digit of the called number.

Since in the present example 6 is the last digit transmitted the wiper 318 is connected with mask conductor 311 and the wiper 316 with combination conductor C6. Referring now to the ringing combination chart it will be seen that the code transmitted will consist of four short rings followed by one long ring.

During the establishment of a reverting call connection to the reverse signal relay 321 is periodically operated over a circuit which extends from battery through the winding of relay 321, conductor 214, contacts 31 of the busy relay 230, conductor 213, contacts 362, to reverse signal conductor REV.SIG. which is periodically grounded as will be subsequently explained. The relay 321, upon operating, at its contacts 322 and 323 reverses the generator connection and opens the generator return circuit for bridged ringing lines, to prevent giving the reverting call signal on bridged ringing or ground return lines, at armature 324 and its front contact completes a circuit including the lower winding of drain relay 333, and at its front contact and armature 325 closes a circuit through the upper winding of the ringing relay 343. The ringing relay 343, upon operating, at this time, owing to the energized condition of relay 321, transmits ringing current out over the line to actuate the ringers which are connected to the line conductor opposite the one to which the ringer of the called station is connected so that if the ringer of the calling station is not on the same side of the line as is the ringer of the called station the calling subscriber will be signalled by operation of ringing relay 343, while relay 321 is operated, to notify him that the called station is being signalled. The relay 321 is only actuated during silent periods of the code as will be subsequently explained.

From the foregoing it will be appreciated that a subscriber making a reverting call who also has his ringer connected to the same line conductor as the called station, will hear the code signal. However, should the ringer of the called station be connected to the other conductor, instead of hearing the code signal he will receive a succession of short rings as long as the called party is being signalled.

The drain relay 333, which, during the signalling operation of a called line, which is not also a calling line, is operated solely over the drain lead DR1 is now also operated over the circuit including contacts of relay 321. Also, just before ground is removed from the reverse signal lead REV.SIG. ground is supplied over the drain lead DR2 and through contacts 32 of the busy relay to the upper winding of relay 333 to battery to hold relay 333 operated for a short interval after relay 343 restores. When ground is removed from the reverse signal lead REV.SIG., the circuit to relay 321 is opened. Relay 321, upon restoring, at its armature 325 transfers the lower winding of relay 333 from ground to the drain lead DR1, thus interrupting the circuit of this relay; at armature 325 transfers the upper winding of relay 343 from ground to the selected mask conductor 311 or 312, thus opening the circuit of relay 343; and at armatures 322 and 323 reverses the generator connection and prepares a generator return circuit for bridged ringing lines. Relay 343, upon restoring, as in the previous description of its operation, removes generator current from the called line, and connects ground

and battery, respectively, thereto, to discharge the condensers in series with the ringers of the called line. When ground is removed from the drain lead DR2, the circuit to the winding of relay 333 is opened. This latter relay, upon restoring connects the tip conductor 303 to ground through the winding of relay 347, and connects the ring conductor to battery through the resistance R21 to prepare the link for releasing when the call is answered.

When the call is answered the ring cut-off relay 347 operates either between signals of the code or between codes, over a circuit extending from battery through resistance R21, the front contact 15 and armature 38, conductor 203, contact and armature 385, contact and armature 345, contacts 366 to the ring conductor 302 and through the called line and the responding station thereon back to tip conductor 303, contacts 365, armature 20 344 and its resting contact, armature 344 and its resting contact, the armature and front contact of relay 349, and the winding of relay 347 to ground. The relay 347, upon operating, at its contacts 348 completes a locking circuit for itself, 25 at its contacts 352 and 353 applies the ground potential from contacts 37 of relay 230 over conductor 207 to conductor 104 and over the previously traced circuit to relay 186, thereby short circuiting it; and preventing its operation. The 30 relay 347 also, at its contacts 350 opens the locking circuit of relay 230, at contacts 351 removes ground from the generator start lead GEN.ST.; at contacts 356 opens the locking circuit to relay 358, and of relays 326 and 332 if they are operated.

The relay 230, upon restoring, at its armature 38 transfers the circuit of relay 229 to the loop of the calling line, at contacts 37 removes the short circuit from the winding of relay 186, at 40 contacts 35 opens the circuit of relay 195; and at the front contact and armature 34 opens the previously traced circuit, extending from ground on the contacts 265 of relay 263 heretofore employed to maintain the line cut-off relay 135 and 45 relays 229 and 235 of the link operated.

Relay 186, upon operating, at contacts 189 removes ground from the time start lead 709, and at contacts 188 disconnects the lower winding of time release relay 181 from the time pulse lead 50 707.

Relay 195, upon restoring, at contacts 197 opens the circuit of relay 235, and at contacts 198 opens the circuit of relay 263, allowing these relays to restore. From this point on the release 55 of the link is brought about in the same manner as when a calling subscriber replaces his receiver at the termination of the connection previously described, except that the relay 347, upon restoring, opens the loop circuit to relays 186 and 229, 60 thus allowing them to restore. The link circuit is now at normal and is again available for pre-selection by the allotter.

The cut-off relay 135 restores when ground is removed from the wiper 385 of the connector 65 by release of relay 230; at armature 140 opens the circuit to the winding of relay 141 and applies ground to the permanent alarm lead, labeled "To relay 3000"; and at contacts 136 and 137 reconnects the line relay 131 in bridge of the calling line. The relay 131 operates over the calling 70 loop, at contacts 134 closes a locking circuit for relay 141, thereby preventing the reapplication of ground potential to the start lead 410 at this time, at armature 133 disconnects the cut-off 75 relay 135 from the test lead 1 to the connector

bank and grounds this lead to make the calling line busy to the other calls. The calling and called subscribers on the same line are supplied with talking battery through their line relays 131, and may now hold a conversation.

When both subscribers on the line replace their receivers the circuit to the line relay 131 is interrupted and it accordingly restores. The relay 131, upon restoring, at its armature 133 removes ground potential from the connector normal 10 again making the line available to other subscribers, and at its contacts 134 opens the locking circuit through the lower winding of relay 141. The latter relay, upon restoring, again places the line in readiness for the initiation of 15 a subsequent call thereover, and at its contacts 144 removes ground potential from the permanent alarm lead.

Private branch exchange calls

20

The first digit of all daytime calls to a private branch exchange are assigned the digit "two". The transmission of this digit, as previously explained, prepares the link for selecting lines in the first hundred group and for signalling with 25 generator applied over the tip lead 302 of the link.

To secure automatic trunk of P. B. X. line selection pins are inserted in the rotary control bank R. C. B. at positions associated with all except 30 the last trunk in each group. These pins are successively engaged by the rotary control wiper RCW to control the stepping relay 295. For example, when the called P. B. X. line is busy the test wiper 385 will encounter ground potential 35 thereby causing the operation of busy relay 230. This relay, upon operating, at its contacts 28 completes a circuit for relay 295. This circuit extends from battery through the winding of this relay, contacts 28, conductor 220, contacts 330, 40 contacts 371, conductor 222, contacts 276, the rotary control wiper RCW and its bank via one of the pins therein, the back contact and armature of magnet 233, conductor 223 and ground at contacts 243. Relay 295, upon operating, at its 45 lower contacts completes a holding circuit for itself excluding the contacts 28 of the busy relay, and at its upper contacts closes a circuit to the rotary magnet 233. This circuit extends from ground through contacts 260, the upper contacts of relay 295, and the lower winding of relay 266 and magnet 233 to battery.

The magnet 233, upon operating, at its armature 55 interrupts the circuit of relay 295 which accordingly restores, and at its upper contacts interrupts the circuit of magnet 233. The armature of magnet 233, upon restoring, at its resting contact again applies ground potential to the rotary control bank and now through the associated wiper RCW, contacts 276, conductor 222, 60 contacts 371, 330, conductor 220, and through contacts 28 of the busy relay to the winding of relay 295 to battery. The relay 295 accordingly again energizes to reestablish the operating circuit of the rotary magnet 233. The interaction of relay 295 with the rotary magnet 233 continues until an idle trunk is encountered. When this occurs battery over the test conductor 210 completes the previously traced circuit through 70 the test relay 228 and at its contacts 24 opens the locking circuit of busy relay 230; at contacts 21 grounds the generator start lead, and at contacts 23 applies direct ground to the test conductor 210 to make the trunk busy to other calls. 75

The relay 280, upon restoring, at contacts 28 opens a point in the circuit of relay 295, to prevent further rotation of the connector. The relay 266, upon restoring, closes the circuit for relay 290, as in the previous description. The operation of relay 290 and the subsequent operations occurring are the same as those described as occurring when an idle individual line was called.

If all the P. B. X. trunks of the called group are busy, the circuit for reoperating relay 295 is opened at the rotary control bank RCB when the connector wipers encounter the last trunk of the group. Under these circumstances, the relay 266, upon restoring, closes the circuit of relay 290 which at its front contact and armature 294 closes the busy tone circuit to advise the subscriber that all P. B. X. lines of the group are busy. The operations from this point on are as explained when a busy individual line is called.

Each P. B. X. group of trunks may have night listings as individual lines by assigning them a second directory number. For example a three line group identified as P. A. X. No. 2411 may be listed for night service as lines 3411, 3421, and 3431, respectively.

The transmission of the first digit "3" brings about the energization of relay 332 which prepares the link for applying generator out over the ring conductor 303 of the link instead of over the tip conductor thereof. This makes no difference, however, in the case of a P. B. X. line as bridged ringing is employed thereon. However, the relay 332, it will be observed, at contacts 330 opens a point in the previously traced operating circuit of stepping relay 295 thereby preventing the trunk-hunting operations previously described occurring. Therefore, the operations which follow will be the same as those following the setting up of a connection to any other individual line of the exchange.

Outgoing toll trunk calls

As previously mentioned, the subscribers of the community exchange have access to three groups of outgoing trunks extending to distant exchanges and these are available by way of the first, second, and third levels of the first hundred group connector bank. A subscriber desiring to initiate a trunk call simply removes his receiver to enable the association of a link with his line, and upon receiving dial tone dials a digit 8, 9, or 0, in accordance with the group or exchange desired.

In order to explain the operation, it will be assumed that a subscriber at substation 5951 desires a connection with a station of the distant exchange made available to him by dialling the digit 0. The repeating relay 246 responds in the manner previously described to operate the class and code switch CC. When, however, the wiper 318 of this switch encounters the seventh bank contact and the magnet 320 restores, a circuit is completed for a change-over relay 296. This circuit extends from battery through the lower or operating winding of this relay, the front contact and armature 274, contacts 282 and 288, conductor 225, the wiper 318 and its associated seventh bank contact, and the back contact and armature of magnet 320 to ground. The relay 296, upon operating, at its contacts 296' closes a point in the operating circuit of relay 253, and at its lowermost armature opens the traced circuit to the rotary magnet 320 and transfers the impulsive circuit to the vertical magnet 234

of the connector mechanism of the link so that the remaining three impulses of the series are transmitted to the vertical magnet 234. This magnet, upon operating effects the positioning of the wipers of the connector opposite the third level of its associated bank contacts via which trunks are available to the desired exchange. The relay 296, upon operating, also at contacts 298 completed a circuit for the busy relay 230. This circuit extends from the grounded armature 274 and its working contact, contacts 288, contacts 279, through armature 272 and its working contact, contacts 24 and the winding of relay 230 to battery. The relay 230, upon operating, at its contacts 28 completes a circuit for relay 295. This circuit extends from the grounded conductor 217 through contacts 291, off normal springs ON21 and its working contact, contacts 299, conductor 220, contacts 28, and the winding of relay 295 to battery. The relay 295, upon operating, at its lower contacts extends this ground potential to the rotary control bank RCB, and at its upper contacts closes a point in the initial operating circuit of the rotary magnet 233.

At the conclusion of the impulse series the relay 270, upon restoring completes a circuit for relay 284 from battery, through the winding of this relay, the back contact and armature 275, working contact and off normal springs ON21, and the contacts 291, to the grounded conductor 217. The relay 284, upon operating, at its armature 285 transfers the impulsive circuit from association with the vertical magnet 234 into operative relation with the rotary magnet 233, by way of the lower winding of relay 266, as in local connections. The relay 270, upon restoring, also at its armature 271 and resting contact completes the previously traced circuit including the release magnet 319 of switch CC and the upper winding of relay 253. Owing to the high resistance of relay 253 compared to that of magnet 319, the magnet does not operate. The relay 253, however, operates and locks up through its lower winding and the grounded conductor 107', and at contacts 260 completes an operating circuit for the rotary magnet 233. This latter circuit extends from battery through the winding of magnet 233, the lower winding of relay 266, the upper contacts of relay 295, and the contacts 260 of relay 253 to ground. The magnet 233 accordingly energizes to advance the wipers of the switch into engagement with the bank contacts to which the first trunk of the selected group are connected. The relay 253 also, upon operating, at its contacts 255 places a shunt about the upper winding of relay 266 enabling it to restore when the intermittent operation of the rotary magnet 233 ceases.

If the first trunk line encountered is busy the test wiper will encounter ground potential thereby preventing the operation of the test relay 288 which is at this time connected to conductor 210. The conditions are now the same as when a busy P. B. X. trunk is encountered and, accordingly, automatic trunk hunting will occur in the same manner, until an idle trunk is encountered or the last trunk of the group is reached.

When the connector wipers encounter an idle trunk, instead of encountering ground potential the test wiper of the switch, will encounter battery supplied through the winding of the cut-off relay such as 1351 of the trunk line equipment TLE, for example, which will operate in series with the relay 228. The relay 1351, upon operating, at its contacts 1361 and 1371 disconnects

the line relay 1311 from in bridge of the trunk, at its contacts 1391 removes the normal connection of battery to and the associated resistance from in multiple with its own winding, at its 5 contact and armature 1401 opens a point in the permanent alarm circuit and completes a circuit through the lower winding of relay 1411 to battery, and at its contacts 1381 extends ground potential to the test contact 150 in the finder multiple. The relay 1411, upon operating, at its armature 1431 interrupts a point in the finder start circuit, and at contacts 1441 closes a point in the permanent alarm circuit.

The relay 228, upon operating; at its contacts 15 24 interrupts the circuit of busy relay 230 permitting it to restore; at contacts 23 applies ground potential to the conductor 210 to maintain the cut-off relay 1351 of the trunk line equipment operated, and to maintain the same 20 busy to other links; at its contacts 22 closes a point in a circuit including the winding of relay 336; and at its contacts 21 applies ground potential to the GEN. ST. conductor 221.

The relay 230, upon restoring, at contacts 28 25 opens a point in the circuit of relay 295 to prevent further operation of the rotary magnet. A slight interval after the last impulse has passed through the relay 266 and magnet 233, the relay 266 restores, and at its contacts 268 completes a circuit 30 of relay 290. The relay 290, upon operating, at its contacts 281 opens the locking circuit of relay 284 and at contacts 292 completes an operating circuit for the relay 336. This circuit extends from battery extending through the 35 resistance R24, armature 22 and its working contact, contact 292, armature 297 and its working contact, conductor 216, and the winding of relay 336 to grounded conductor 107. The relay 336, upon operating, at contacts 338 completes a locking 40 circuit for itself, at contacts 342 applies ground potential to the conductor 119, in order to maintain the relay 175 operated independent of contacts 193 of relay 190; at contacts 339 connects the finder test conductor 210, also that 45 ground potential is now maintained on both these conductors via armature 191 and its front contact; and at armatures 337 interrupts holding circuits of relays 358 and 296.

50 The relays 358 and 296 accordingly restore. The relay 336, also, at armatures 340 and 341 interrupts the previously traced circuits extending from the calling line to conductors 202 and 204 through the windings of link line relays 245 and 349 and substitutes therefor the conductors 302 and 303 now extended into connection with trunk conductors 701 and 702. The conductor 701 extends via armature 718 and at its resting contact through the upper right-hand winding 60 of repeating coil R1 and the winding of relay 712 to battery, while the conductor 702 extends via armature 780 and its resting contact, and lower right-hand winding of the repeating coil R1 and winding of relay 717 to ground. Obviously, 65 the result of the operation of armatures 340 and 341 of relay 336 is the substitution of relays 712 and 717 in bridge of the calling line for relays 245 and 349 formerly in bridge thereof. Since the calling line is in bridge of the trunk relays 712 and 717, these relays now operate. The relay 712, upon operating, connects ringing tone to the conductor 701 by way of the upper armatures and contacts of relays 715, 716, and 720, to advise the calling subscriber that the operator 75 at the distant exchange is being signalled.

The relay 717, upon operating, at its lower contacts completes a circuit, via armature 788 and its resting contact and conductor 788 to the relay 719; and also, via the resting contacts and armature 790, to the relay 718; and at the 5 inner contacts completes an obvious operating circuit for the reversing relay 724. The relay 719, upon operating, at its armature 781 interrupts a point in the operating circuit of relay 711, and at its working contact closes a circuit to the 10 generator start lead. The relay 718 also at its armature 782 connects the test conductor 704 of the connector multiple to ground by way of the upper winding of relay 722, and contacts controlled by the armature 7892 of relay 723 to re- 15 place ground being supplied thereto from the working contact and armature 191, over the test conductor 210 of the link.

The relay 718, upon operating, at contacts 766 closes a point in an operating and locking circuit 20 of alarm control relay 723, at armature 778 and its front contact applies ground potential via contacts 757 to the solenoid 750 and via contacts of relay TC1 to the winding of relay 751 of the time cut-off equipment, and at contacts 771' completes 25 the circuit of relay 721. This latter relay, upon operating, closes points in a paystation tone circuit including the lower winding of relay 722.

The relay 724, upon operating, reverses the ground and battery connections with respect to 30 the trunk conductors T1 and T2, thereby bringing about the energization of the polarized relay 726 of the operator's equipment. The relay 726, upon operating, completes an obvious circuit for relay 727. The latter relay, upon operating, at 35 its contacts 1851 completes a circuit for the drop D which operates as a call signal before the operator; at contacts 1861 closes a point in the locking circuit of relay 727, and at contacts 1871 closes a point in an alternative operating circuit for the 40 drop D.

The operator responds by inserting the plug of her cord circuit in jack J' which mechanically actuates springs 765 and 766. The springs 765 close a point in the second operating circuit of 45 drop D, while the springs 766 close the circuit of relay 728. The relay 728, upon operating, at its upper outer contacts interrupts the existing circuit through the drop D, permitting it to restore to normal; at its inner upper contacts places a 50 shunt around the upper high resistance winding of the polarized relay 726, thereby increasing the current flow over the trunk conductors T1 and T2 sufficiently to enable the operation of relay 713, and at its lower contacts completes the lock- 55 circuit of relay 727.

Relay 713, upon operating, at its upper contacts closes a point in an impulsive circuit employed in incoming calls, and at its lower armature and front contact completes a circuit for 60 relay 714. The relay 714, upon operating, at its contacts 770 completes the circuit of relay 720. The relay 720, upon operating, at its uppermost contacts interrupts the ringing tone circuit, at armature 781 removes ground from the generator start lead, at armature 790 interrupts the circuit of slow release relay 718. If the calling station has a paystation the current flowing through the upper winding of relay 722 will be of a character to induce a tone current in the lower winding of this relay which will serve to notify the operator that a paystation line is calling. An instant later this tone is cut off by the restoration of relays 718 and 721.

In the link circuit, although the relay 249 has been disconnected from the line, it does not restore owing to its locking circuit remaining intact.

5 The relay 245, however, restores and at its lower contacts interrupts the circuit of relay 246 and at its upper contacts removes ground at this point from connection with the conductor 114. The relay 246, upon restoring, removes ground 10 from conductor 114, thereby permitting the slow release relay 194 to become deenergized; and at its back contact transmits an impulse out over the previously traced pulsing circuit to the slow release relay 263. The operation of this relay 15 is of no particular utility at this time.

The slow release relay 194, upon restoring, interrupts the circuit for release relay 190 and that relay accordingly restores. The relay 190, upon restoring, at its armature 191 removes 20 ground potential from conductor 106 at this point, but without effect since previous to this time substitute ground potential has been supplied to the conductor 106 by the operation of relays 336 and 719 as previously described; at 25 contacts 193 opens the initial holding circuit for relay 175, but without effect because of the substitute holding circuit for it established by contacts 342 of relay 336; and at its contacts 192 removes ground potential from the winding of 30 relay 195, which accordingly restores. The relay 195, upon restoring, at its contacts 197 opens the operating circuit of relay 235 which, however, remains energized over its locking circuit; and at its contact 196 interrupts a point in the circuit 35 for slow release relay 263 completed upon restoration of the line relay 246. The relay 263 therefore restores.

Since the calling subscriber is now supplied with talking battery through the relays 712 and 40 717 of the trunk equipment conversation with the operator may be carried on by way of the repeater R1, trunk conductors T1 and T2, the repeater R2, and by way of the talking equipment associated with the cord employed in answering the 45 connection.

When the conversation is complete and the calling subscriber replaces his receiver, relays 712 and 50 717 restore to normal. The relay 717, upon restoring, at its lower contacts removes ground 55 from the operating circuit of slow release relay 719. The relay 719, upon restoring, at its armature 782 removes ground from conductor 704 and from the test conductor 210 of the connector end of the link, and which has also been supplying ground through contacts 339 to the test conductor 106 of the finder end of the link. The removal of ground potential from conductor 106 and consequently from its branch conductors 199 and 115 effects the deenergization of relay 235. 60 The relay 235, upon restoring, at contacts 236 removes ground potential from conductor 107, thereby causing the restoration of relays 253 and 336. The relay 235, at its contacts 242 effects the restoration of the switch CC and of the finder 65 and connector mechanism in the manner previously described. The relay 336, upon restoring, at its contacts 342, interrupts the circuit through the lower winding of test relay 165, which, accordingly, also restores. The link circuit is now 70 once more in its normal condition in readiness for selection by the allotter. The relay 717, upon restoring also, at its inner contacts opens the circuit of relay 724. The relay 724, upon restoring, reverses the ground and battery connections 75 of relays 713 and 725 with respect to the trunk

conductors T1 and T2, thereby bringing about the deenergization of polarized relay 726. This relay, upon restoring, at its armature and resting contact now completes a circuit through contacts 187, and springs 765, and through the drop 5 D, thereby operating it as a disconnect signal to the operator.

Upon removal of the plug from the associated jack the relay 728 again restores. Relay 728, upon restoring, at its break contacts again closes 10 a point in the original operating circuit of drop D, at its upper make contacts removes the shunt from about the high resistance winding of polarized relay 726, and at its lower contacts interrupts the locking circuit of relay 727, permitting 15 that relay to restore. Upon removal of the shunt about the upper winding of relay 726 the relay 713 restores and at its lower armature interrupts the circuit of slow release relay 714. The relay 714, upon restoring, interrupts the circuit of relay 720 which accordingly also restores, 20 placing the apparatus again in readiness for use on subsequent calls.

Incoming toll trunk calls

25

It will now be assumed that in response to a call in the distant exchange a local subscriber is desired in a trunk connection. The operator at the distant exchange will accordingly plug in one of her cord circuits into an idle trunk jack 30 extending to the desired local exchange. It will be assumed that the trunk shown in Fig. 7 is the one selected. When the plug of the operator's connecting cord circuit is inserted in the jack J' of the trunk circuit TR the high resistance winding of relay 726 will be shunted and the relay 713 of the trunk equipment will accordingly operate. The relay 713, upon operating, at its lower armature and working contact completes the previously traced operating circuit of relay 714. 40 Relay 714, upon operating completes the circuit of relay 720 at its contacts 770, and at its contacts 776 completes a circuit for slow release relay 711. This latter circuit extends from battery through the lower winding of relay 711, the 45 contacts controlled by armature 782, contacts 776, and the back contact and grounded armature 781 of relay 719. The relay 711, upon operating, now completes a circuit in bridge of the trunk conductors 701 and 702 which extends from 50 conductor 701, through the armature 778 and its working contact, springs controlled by armature 773, the upper winding of relay 711, the contacts 791 of relay 713, and the front contact and armature 780 to the conductor 702. The 55 bridging of the upper winding of relay 711 across conductors 701 and 702 effects the operation of the line equipment of the trunk in the same manner as is the subscriber's line equipment effected upon a calling subscriber removing his receiver, 60 accordingly the line relay 1311 operates to ground its associated start conductor and, in the same manner in which the subscriber initiates a call, causes the preselected link circuit to become associated with the line and test terminals 146, 148 65 and 150 of the incoming trunk. The operator, upon receiving dial tone, inserts the dialling plug P into the jack J, thereby substituting the calling device springs in bridge of the trunk conductors T1 and T2 for the winding of the polarized relay 726, and proceeds to dial the digits of the called number. The relay 713 is intermittently deenergized in response to the operation of the calling device CD, and at its contacts 791 70 interrupts the circuit of relay 711 and of line 75

relay 245 of the link circuit in substantially the same manner as does the calling subscriber of the local exchange. The relay 713, also, upon first restoration, completes a circuit to the slow release relay 715 which energizes and remains operated throughout each impulse series. This circuit extends from the grounded armature and resting contact of relay 713, through contacts 771, conductor 784, armature 785 and its resting contact, and the winding of relay 715 to battery. The relay 715, at its contacts 786', places a shunt about the upper winding of relay 711 so as to exclude the resistance of the upper winding of this relay from the impulsive circuit during the actual transmission of impulses. The relay 715 also, at contacts 789' completes a circuit, via contacts 772 and armature 779' and its working contact, for the relay 716. This latter relay, upon operating at contacts 775 completes a locking circuit for itself, including contacts 776 and the back contact and grounded armature 781. The relay 716 at contacts 772 interrupts its initial operating circuit; at armature 782 completes a locking circuit for relay 711, excluding the contacts 776 of relay 714; at contacts 771 opens a point in the ringing tone circuit employed on incoming calls only; at contacts 774 applies ground potential, from springs of armature 7892, to test conductor 703 and to its test contact 750; and at armature 773 opens the bridge from across conductors 701 and 702 and connects battery through the associated resistance and through contacts 786', 791, and 780 to conductor 702 and over the extended link circuit to the winding of link line relay 245 and ground.

Shortly following the completion of the dialling operation relay 715 restores and at contacts 789' opens the traced locking circuit of relay 711, and at contacts 786 includes the upper winding of this relay in the circuit including line relay 245. Also following the completion of the dialling operation relay 253 of the link circuit operates as in local connections and at its contacts 258 removes the resistance R21 and battery from in multiple with line relay 349. Since, however, in the present connection relay 349 has its operating circuit held open by the contacts controlled by armature 773 of the trunk circuit relay 716, the relay 349 does not operate at this time. The operator having completed the dialling operation, removes the plug P from the jack J, thereby placing the polarized relay 726 again in bridge of the trunk conductors T1 and T2. Assuming the line to be idle, the operator will receive ringing tone to notify her that the called subscriber is being signalled in the same manner as does a subscriber of the local exchange.

When the called party answers, ring cut-off relay 336 and back bridge relay 229 operate and produce circuit changes substantially identical to those resulting upon the response of a trunk call initiated in the local exchange.

As in trunk connections originating in the C. A. X., release is brought about by the removal of ground potential from conductor 106 and its branches 199 and 115. This is brought about by the operator's withdrawal of his cord from jack J', resulting in the restoration of relay 713. This relay in restoring interrupts the circuit of relay 714. The relay 714, upon restoring, at contacts 770 interrupts the circuit of relay 720, permitting it to restore; and at contacts 776 interrupts the locking circuit of relay 716. The relay 716 accordingly restores and at its contacts 774 removes ground from conductor 703 over which ground

has up to this time been supplied to conductor 106 via bank contact 150 and wiper 151.

Time cut-off features

Time cut-off arrangements have been provided for freeing the link and trunk circuits when the same are held by a permanent line under the following conditions: (1) when the calling subscriber fails to complete a connection to the called line; (2) when the calling subscriber fails to hang up his receiver after a completed call; and (3) when the calling subscriber fails to hang up his receiver after receiving the busy tone. The time cut-off relays TCO, shown in Fig. 7, have their operation initiated consequent to the seizure of a trunk or link, and effect the operation of the relay 723 of the trunk or 181 of the link, if the connection fails of completion within a predetermined period.

As previously described, when a link circuit is seized, the relay 235 operates and at its contacts 240 applies ground potential to the time start lead 709 extending to the time cut-off relay 751 and solenoid, respectively. Relay 751 operates and sets its weighted spring into vibration thereby closing an intermittent circuit to relay 752. This latter relay is slow to operate and does not operate until the vibration of the springs of relay 751 have practically ceased. Relay 752 finally operates, however, and at armature 753 removes ground potential from the branch 763 and from the time cut-off conductor 708 and connects these conductors to the upper winding of alarm relay 760. The relay 752 also, at contacts 754 closes circuits through the right-hand winding of relay TC1 and to the winding of relay 756, respectively. Relay TC1 operates and opens the circuit of relay 751 and closes a locking circuit for itself including its left-hand winding and the grounded time start lead 709. Relay 756 operates, and, at contacts 758 disconnects the time pulse lead 707 from the time pulse alarm lead extending to the lower winding of alarm relay 760. The relay 756 also, at contacts 757, opens the circuit to the solenoid 750.

Owing to the operation of relay TC1 and the fact that the circuit of solenoid 750 has been interrupted, relay 751 restores and opens the circuit of relay 752. Relay 752, upon restoring, at contacts 754 opens the circuit of relay 756 and that extending through the right-hand winding of relay TC1, and at armature 753 disconnects the time cut-off leads 763 and 709 from the upper winding of the alarm relay 760 and again grounds these leads. The relay 752 also, at contacts 755, via contacts 758, now grounds the time pulses lead 707 to cause the link and trunk circuits which have been seized but which are not in talking position to prepare to cut off.

Relay 756, upon restoring, at armature 758 removes ground from the time pulse lead 707 and reconnects this lead to the lower winding of alarm relay 760, and at contacts 757 reconnects the solenoid 750 to the time start lead 709. After a predetermined interval, solenoid 750 again operates and finally closes the circuit to relay 751. Relays 751, 752, and 756, accordingly, reoperate in the manner previously described. When the circuit to 750 is opened by 756, 750 restores and opens the circuit to 751. Relays 751, 752 and 756 accordingly restore in the manner previously described. The foregoing cycle of operations continues until ground is removed from the time start lead 709. From the foregoing it will be seen that following the seizure of a link and upon operation of its

slow release relay 195 the relay 181 will be operated by the subsequently transmitted pulse over the time pulse lead 707. The relay 181, upon operating, at its armature 182 and its front contact completes a locking circuit for itself independent of the conductor 707 and of the time cut-off relays, at armature 183 removes direct ground potential from the circuit extending to the lower winding of test relay 175 and substitutes therefor ground supplied over the time cut-off lead 708; at contacts 185 disconnects one of the multiple ground connections from the all-link busy lead 403; and at contacts 184 applies ground potential to the guard conductor 401 independent of that supplied through the contacts of relay 235. If the link reaches talking condition before ground is removed from the time cut-off lead 708, as will be the case under normal conditions, relay 186 will energize over the called loop and at its contacts 188 open the circuit of relay 181, thereby causing it to become deenergized. The relay 181, upon restoring, at the springs controlled by armature 183 reconnects direct ground potential by way of contacts 193 to the winding of test relay 175 to hold such relay in its energized position.

If, however, relay 186 does not energize before ground is removed from the time cut-off conductor 708, then disconnection of ground from such conductor by the operation of relay 175 causes the deenergization of the test relay 175. The relay 175, upon restoring, at its contacts 176 and 177 interrupts the circuit of line relays 245 and 349 of the link, thereby causing their deenergization. The deenergization of the latter relays causes the relays in the link to restore to their normal position in the same manner as previously described. Under these conditions the slow release relay 195, upon restoring, at contacts 198 opens the locking circuit of relay 181 to permit the latter relay to restore. The relay 181, upon restoring, at its contacts 184 removes ground from the guard lead 401 to free the link.

The time release relay 722 in the trunk TR, Fig. 7, prevents the trunk line from being indefinitely held up in case the operator fails to answer, or in case the calling subscriber fails to hang up his receiver after conversation after the operator has disconnected. After the conversation has been terminated the operator disconnects her cord from the trunk, thereby causing the deenergization of relays 713, 714, and 720, as previously described. In case the subscriber fails to replace his receiver the slow-release relay 718 again operates over the previously traced circuit following the restoration of relay 720. The relay 718, at its contacts 718 applies ground potential to the time cut-off start lead 709, and at its contacts 766 connects the upper winding of the time release relay 723 with the time pulse conductor 707. When the time pulse conductor becomes grounded relay 723 becomes energized and at its armature 787 completes a locking circuit for itself independent of the time pulse conductor, at its armature 784 transfers the upper winding of relay 722 from direct ground at the normally closed springs controlled by this armature to ground on the time cut-off conductor 708, and at its contacts 786 closes a point in a circuit for directly grounding the test conductor 704. If the trouble condition continues, ground is disconnected from the time cut-off conductor 708 after an interval, and this disconnection of ground opens the series circuit including relay 722 and trunk line cut-off relay 1351. This

ground up to this time has also extended via armature 1331 and its resting contact and contacts 1381 to the test contact 150. The removal of this ground also opens the circuit of relay 235 of the link. When the latter relay deenergizes the link circuit is restored to its normal condition in the manner previously described. The deenergization of the cut-off relay 1351 restores the trunk line circuit to its normal condition. When the relay 722 restores it opens the traced locking circuit of relay 718 if such relay is operated. When the link circuit releases the relay 175 opens the circuit extending to relays 712 and 717 which now deenergize. The relay 717 in turn opens the circuit of slow release relay 718 and the circuit of relay 724. The relay 718, upon restoring at contacts 766 opens the circuit of relay 723 permitting it to restore, thus placing the trunk TR in normal condition.

Ringing equipment and code interrupter control 20

The start relay 620, as explained, operates in response to the energization of one of the relays 228 or 229 of a link or in response to the operation of a relay 718 of a trunk. The relay 620, at contacts 621 applies ground potential to conductor 508 and through the windings of relays 535 and 566 to battery, to start the code interrupter to function and to open the alarm leads of reverse signal REV. SIG., drain DR1, and of mask conductors 311 and 312, so that the alarm equipment will not interfere with the operation of the ringing control relays in the link circuits. The relay 620 also, at contacts 623, completes a circuit for relay 635, at contacts 624 completes a circuit for relay 552 and at contacts 625 applies ground potential to conductor 513. The relay 620 finally, at contacts 622 completes a circuit for pole-changing relay 658 or 658' depending upon the operated or non-operated condition of key K2. The position of this key determines which of the first two pole-changing relays will be first choice. In the drawings the key K2 is shown at normal and therefore the circuit of relay 658 will be the one completed at this time. The circuit for relay 658 extends from ground through contacts 622 of relay 620, contacts 630, conductor 512, resting contact and armature 541, conductor 511, conductor 668, armature 650 and its resting contact, and the winding of relay 658 to battery. A second circuit to conductor 668 in multiple with the one traced includes resistance R6 initially shunted by contacts 630. The relay 658 now operates with large amplitude for starting and prepares to short circuit its winding. When the master interrupter relays 535 and 534 complete their first cycle, as will subsequently be described, the circuit to the lower winding of relay 627 is completed.

The relay 627, upon operating, at contacts 628 connects conductors 668 and 669 together and in this way transfers the control of the operation of the pole-changing relay 658 from relay 536 to relay 627. The relay 627 at its contacts 629 closes a point in the odd code forming relay control circuit, at contacts 630 removes ground potential from conductor 512, and at its contacts 667 completes a locking circuit for itself including its upper winding. The relay 627 also at its contacts 631 interrupts the circuit of the reverse signal alarm relay 552, and at contacts 632 and 633 connects the primary winding of the ringing transformer RT by way of armatures 645 and 646 and their resting contacts with conductors 663 and 664. Since these conductors, as pre- 75

viously explained, are alternately supplied with battery by armature 666 current will flow through the primary winding of the ringing transformer to produce ringing current in the secondary winding. A portion of this ringing current flows through condenser C61 and through the winding of alternating current relay 626 to ground. The relay 626 accordingly operates and at its contacts interrupts the circuit of relay 635 before the same has been energized a sufficient period to bring about the energization of slow to operate relay 637.

If, however, the pole-changing relay 658 fails to deliver alternating current the relay 635 will finally bring about the energization of slow to operate relay 637. This latter relay, upon operating, at its contacts 639 opens the circuit of the generator start relay 620, and at its contacts 638 completes an operating circuit for the ringing machine switching relay 640. This latter circuit includes contacts of key K2, contacts 6414 of relay 6411 and the lower winding of relay 640 to battery. This latter relay, upon operating, at contacts 643 completes a locking circuit for itself including ground supplied via the manually operable key K1. The relay 640 also, at its armatures 642 and 650, transfers the operating circuit connections from relay 658 to 658', and at armatures 645 and 646 transfers the connections of the primary of the ringing transformer RT from conductors 663 and 664 to the conductors 660 and 631 of pole-changing relay 658'. The relay 640 also, at its contacts 644 applies ground potential over conductor 516 to the winding of alarm relay 557 to battery.

The start relay 620, upon deenergizing, at contacts 621 removes ground from the conductor 508, thereby causing the code interrupter relays which may be operated at the time to restore, at contacts 622 opens the locking circuit of relay 627 permitting that relay to restore, and at contacts 623 interrupts the circuit of relay 635. The relay 635 accordingly restores and opens the circuit of slow operating relay 637. This latter relay, upon restoring, at its contacts 639 again establishes the circuit of start relay 620. The relay 620, upon operating, restarts the cycle of operation just described and, assuming that the pole-changing relay 658' is functioning properly, relay 626 will operate in time to prevent a second interruption of the generator start circuit.

If an attendant desires to transfer the ringing equipment back to the first relay 658 he operates the key K1 momentarily, thereby interrupting the locking circuit of relay 640. The relay 640, upon restoring transfers the associated circuits back to their initial condition and at its contacts 644 removes ground potential from the alarm lead 516.

The attendant may also, by moving key K2 to its alternate position, make the pole-changing relay 658' first choice. If the key K2 is operated during a time the generator start lead is grounded nothing happens. As soon, however, as the generation of ringing current ceases, the relay 626 will restore and at its contacts apply ground via the key contact and spring K23, contacts 6420, and the lower winding of relay 6416 to battery. The relay 6416 operates, at contacts 6417 closes a point in a circuit including its upper winding, and at contacts 6419 completes a locking circuit for itself including ground supplied through the contact and operated key spring K21. The relay 6416 also at contacts 6420 opens its operating circuit, at contacts 6421 opens the lock-

ing circuit of relay 640, and at contacts 6418 closes a circuit for relay 640. This circuit extends from ground on spring K21, its alternate contact, contacts 6418 and 6414 and the lower winding of relay 640 to battery. Relay 640, accordingly, operates and transfers the conductors 668 and 669 and the conductors extending from the primary winding of the transformer RT to the pole-changing relay 658'. When the generator start lead GEN. ST. is again grounded, the equipment operates as previously explained, except that relay 620 now also extends ground potential to operated contacts 6417 and to the contacts 6415 through the upper holding windings of relays 6416 and 640 to hold them operated independently of the circuits through their lower windings.

Now, if the code interrupter relays fail to complete a cycle of operation or if the relay 658' fails, relays 635 and 637 operate, bringing about the restoration of relay 620, as previously described. Relay 637, this time, upon operating, at contacts 638 extends ground via the contact and operated key spring K22 to the winding of relay 6411 and battery. The relay 6411, upon operating, at contacts 6412 completes a locking circuit for itself including the contacts of key K1; at contacts 6414 and 6415 opens the circuit of both windings of relay 640; and at contacts 6413 applies ground to the alarm lead 516. Relay 640, upon restoring, transfers the pole-changing relays and transformer connections as required for operation of pole-changing relay 658. Relays 635 and 637 subsequently restore and relay 620 reoperates as previously explained.

If the attendant desires to transfer the circuits back to the second pole-changer 658' he may do so by momentarily operating the key K1, to break the locking circuit of relay 6411. This relay, upon restoring, again prepares the circuits of relay 640 and at contacts 6413 removes ground potential from the alarm lead 516.

The attendant may manually transfer the circuits to again give the pole-changer relay 658 first choice, by simply restoring the key K2 to normal. If at the time of restoration of key K2 the generator lead is grounded nothing happens. When ground potential is removed therefrom the relays 620, 627 and 658 come to normal in the usual manner. When relay 620 is at normal, the traced holding circuits of relays 640 and 646 are interrupted at contacts 622. Due to its slow release characteristics, relay 6416 remains operated long enough to prevent a lock-up of relay 640 through the contacts 6421. The relay 640, upon restoring, transfers the pole-changing relay and primary winding of the transformer RT to the relay 658.

As previously mentioned the relay 620, upon operating, applies ground potential to code start conductor 508.

The relay 5661 is directly operated by ground potential supplied over the conductor 508 and at its contacts 5662 to 5667, inclusive, opens the operating circuits of alarm relays 557, 558, 562 and 566, respectively. The relay 535 is also operated over a circuit including ground potential applied over conductor 508 to the lower terminals of relays 534 and 535. The relay 534, however, is prevented from operating at once because of the connection of the grounded conductor 508 to the upper terminal of this latter relay, by way of contacts 543 of relay 535. This latter relay, upon operating, at contacts 543 removes the shunt circuit from around relay 534, at contacts 544

completes an obvious circuit for the master control relay 532 and at armature 545 produces circuit changes which will be described later. The master control relay 532, upon operating, at its contacts 584 closes a point in the odd code forming relay control circuit, and at its lower armature and front contact completes a holding circuit for itself including the upper winding of relay 533 by applying ground potential from the 5 branch conductor 576 of conductor 508 by way of the back contact and armature 586 to the upper winding of relay 533. This latter relay, however, is prevented from operating at this time as it is shunted by ground potential applied to the upper 10 terminal of its upper winding via contacts 544 and its own lower break contacts.

After a slight interval the slow to operate relay 534 becomes energized. This relay, at its contacts 580 places a shunt around relay 535 by directly grounding the upper terminal thereof, and at its contacts 582 completes the circuit of relay 536. The relay 536, upon operating, at contacts 538 prepares an operating circuit for relay 627, at contacts 539 and 540 closes points in operating circuits of masking relays 537 and 551, respectively, and at armature 541 opens a point in the previously traced circuit for relay 658 and ties conductors 510 and 511 electrically together. Battery potential formerly applied to conductor 30 662 by the operated armature 666 now extends by way of resting contacts and armature 642 to conductor 668, the armature 650 and its resting contact, thereby placing a shunt about the winding of relay 658. The armature 666 therefore 35 swings to the left thereby breaking the traced shunt circuit about the relay and permitting the same to again energize this time from ground supplied through contacts 622 of the start relay and through the resistance R6. The relay 658, 40 accordingly, operates its armature 565 back and forth at normal amplitude at a frequency determined by the adjustment of the weight on its armature and in so doing alternately applies battery to the conductors 663 and 664.

The relay 535, a slight interval after being shunted by contacts 580 of relay 534, becomes deenergized. The relay 535, upon restoring, at contacts 543 again establishes the shunt circuit for relay 534, and at contacts 544 removes the shunt circuit from the upper winding of relay 533, thereby permitting it to operate in series with relay 532. The relay 533, upon operating, at its armature 583 opens a point in the odd code forming relay control circuit and closes a point in the even code forming relay control circuit, and at its inner upper contacts establishes a circuit through the upper winding of relay 536 so that it will remain energized after relay 534 restores. The relay 533 also, at its inner lower armature 55 opens a point in its initial shunt circuit and prepares a holding circuit for itself and an operating circuit for the relay 531, and at its lowermost contact closes a point in the knock-down circuit for relay 529 which is ineffective at this 65 time.

Upon the restoration of relay 534 a circuit for relay 627 is again completed from grounded armature 579 and its resting contact, through contacts 538, conductor 507, and the lower winding of relay 70 627 to battery. The relay 534 also at its contacts 580 again removes the shunt from about relay 535, and at its contacts 582 interrupts the circuit through the lower winding of relay 536 which is now maintained energized via its upper winding. 75 The relay 535, accordingly, again operates to re-

move the shunt from relay 534 and at its contacts 544 again completes a circuit for relay 532. The relay 532, upon operating, at its lower armature again prepares an operating circuit for relay 533 and a holding circuit for relay 532, and at its contacts 584 completes the circuit of odd code forming relay 521. This circuit extends from grounded conductor 508, through armature 583 and its resting contact, contacts 585, conductor 506, contacts 629, conductor 505, through the upper break contacts of relays 530 and 529, and the winding of relay 521 to battery.

The code forming relay 521, upon operating, at its contacts 593 closes a point in the operating circuit of even code forming relay 522, at its contacts 592 completes a locking circuit for itself including the break contacts of relay 522 and the grounded conductor 576, at its contacts 590 applies ground potential over conductor 571 and through the inner lower break contacts of relay 530 and the winding of this relay to battery, and at contacts 589 connects the grounded conductor 576 to the masking relay 551 by way of conductor 572 and contacts 540 of relay 536. The relay 521 also at its armature 591 applies ground potential to the drain conductor DR2 to operate the drain control relay 333 of any links which are at this time in the signalling stage of a reverting call connection. The relay 530, upon operating, at its upper contacts opens the initial operating circuit of relay 521, at its make before break contacts opens its initial operating circuit and locks itself up direct to the grounded conductor 576. The relay 521 also, at its upper group of contacts, connects common conductor 517 with the ringing combination conductors C1 to C6, inclusive, and C10.

The relay 534, upon again operating, at its armature 579 opens the initial operating circuit of relay 627 and at its front contact applies ground potential to conductor 517, and through ones of conductors C1 to C6 and C10 of any previously seized link, in ringing position, having their class and code switch in its first to sixth or tenth position to operate their ringing relays, 45 such as 343, of the link shown, and, in the local connection described, through conductor C5, to the fifth bank contact of switch CC, its associated wiper 316, to the armature 360 of the pick-up relay 358, which has not yet operated. 50 The relay 534 also, at its contacts 580 again places a shunt about the relay 535, and at its contacts 582 again closes a circuit through the lower winding of relay 536 so as to maintain that relay energized.

The relay 535, upon restoring a second time, again places a shunt about the winding of relay 534 and again removed the shunt from the winding of relay 533. The latter relay, upon operating, at its armature 583 again opens a point in the odd code forming relay control circuit and closes a point in the even code forming relay control circuit. The relay 533, upon operating, at its front contact and armature 583 now completes a circuit for the even code forming relay 522. The operating circuit for the even code forming relay 522 extends from the grounded conductor 508, through the armature 583 and its front contact, contacts 585, conductor 518, and contacts 593 and 70 winding of relay 522 to battery.

The relay 522, upon operating, at its inner upper make contacts prepares a point in the operating circuit of odd code forming relay 523, at its inner lower make contacts completes a 75

locking circuit for itself including the break contacts of relay 523, and at its make before break combination interrupts the locking circuit of relay 521 and the initial operating circuit of relay 530, 5 and applies ground potential direct to conductor 573 to maintain the masking relay 551 energized independently of the relay 521. The relay 522 also at its upper group of contacts connects the conductor 517 with the code combination leads C1 10 to C6, inclusive, C9 and C10.

The relay 521, upon restoring, at its contacts 593 opens the initial operating circuit of code forming relay 522, at its contacts 592 opens a second point in its own locking circuit, at its contacts 589 opens the initially established circuit of masking relay 551, but without effect in view of the new circuit established for it by relay 522, at its armature 591 removes ground from the drain conductor DR2, and at its contacts 590 15 opens a point in the initial operating circuit of relay 530.

Relay 534 now operates and at its armature 579 again applies ground potential to the conductor 517, this time via contacts of code forming relay 25 522 to the conductors C1 to C6, inclusive, C9 and C10. The relay 534 also at contact 580 again places a shunt about the relay 535, at contacts 582 again completes a circuit through the lower winding of relay 536 to maintain the same operated 30 independent of its upper winding.

After an interval the relay 535 restores, at its contacts 543 again places a shunt about the winding of relay 534, and at contacts 544 interrupts the circuit through the lower winding of relay 533 35 including the upper winding of relay 531. The relay 533 accordingly restores, but relay 531 remains energized through its winding, its contact and armature 586. The relay 533, upon restoring, at contacts 583 opens a point in the even code 40 forming relay control circuit and again closes a point in the odd code forming relay control circuit, at its inner lower armature and its resting contact again closes a point in the circuit of relay 532, and at its lower contacts opens a point in 45 the knock-down circuit of relay 529.

An interval after the restoration of relay 535 the relay 534 restores and at its contacts 582 interrupts the circuit through the lower winding of relay 536. Since the relay 533 is deenergized at 50 this time the relay 536 restores.

On the next operation of interrupter relay 535 it removes the shunt from relay 534, and again closes the circuit of master control relay 532. The master control relay 532 again operates and in 55 terrupts the circuit of relay 531 and prepares a circuit for relay 533 and at its contacts 584 connects the grounded interrupter start lead to the next code forming relay, in this case relay 523. At the end of the impulse, when relay 534 restores, 60 the relay 533 again operates in series with relay 531. The foregoing cycle of operations of relay 531, 532, 533 and 536 under control of interrupter relays 535 and 534 continues until ground potential is removed from the interrupter start conductor 508.

The following chart shows one complete cycle of operation of the code interrupter relays constituting twenty-four periods and shows the first and second periods of the second cycle.

70 The first vertical column indicates the energized condition of the interrupter relays 535 and 534. The second vertical column shows which of the master control relays are operated. The third column indicates which of the code forming relays are operated for the various periods, while

the last column indicates which of the combination ringing and masking leads are grounded during the various periods.

In the same manner as previously described the 30 code forming relays are successively energized to prepare the circuit for the succeeding code forming relays and to open the locking circuit for the preceding code forming relays to cause such relays to deenergize. Each code forming relay is thus 35 energized and during the time that interrupter relay 534 is energized such code forming relay will ground the combination ringing and masking leads as set forth in the foregoing chart. It will be noted that the four code forming relays 521 to 40 524, inclusive, maintain the masking relay 551 continuously energized and consequently the masking conductor 312 is grounded continuously as long as any one of these code forming relays is energized, the first and fourth of these relays completing the circuit for the relay 551 via conductor 45 572 and contacts 540 and the second and third of the code forming relays completing the circuit direct over conductor 572.

When the interrupter relays energize for the 50 ninth period, thereby causing the energization of master control relay 532 and code forming relay 525 the masking relay 537 is energized through the lower contacts of relay 525, over conductor 574 and by way of contacts 539 of relay 536. The masking relay 537 is accordingly operated and at its armature 546 applies ground potential to mask conductor 311. On the subsequent operation of code forming relays 526, 527, and 528, the masking control relay 537 is maintained energized over conductor 575 or alternatively over conductor 574 and through contacts 539 of relay 536, and therefore maintains the mask conductor 311 grounded during the operation of the code forming relays 525 to 528. From the foregoing it will be seen 60 that the mask conductor 312 is maintained continuously grounded from the first to the eighth period and that the mask conductor 311 is continuously grounded from the ninth through the sixtieth periods, as illustrated in the foregoing 65 chart.

The code forming relay 528 is energized during the sixtieth period and at its inner upper make contacts prepares the operating circuit for relay 529, at its inner lower make contacts com- 70 75

plete its own locking circuit, and at its make before break contacts interrupts the circuit of relay 521 and applies ground potential to conductor 574 to maintain the masking relay 537 energized until relay 536 deenergizes.

When the interrupter relays are energized during the seventeenth period, master control relay 532 is energized to complete the circuit of code forming relay 529. The relay 529, upon operating, at its upper contacts opens a point in the initial operating circuit of code forming relay 521, at its inner upper make contacts prepares a point in a circuit for knocking down relay 530, at its inner lower make contacts completes a locking circuit for itself, at its inner lower break contacts opens the locking circuit of relay 528, at contacts 596 opens a point in a circuit for applying ground potential to the pick-up conductor PU, at contacts 597 closes a holding circuit for reverse alarm signal relay 552 providing this relay is operated at this time, at its contacts 599 also closes a point in an operating circuit for the relay 552, and at armature 598 and its front contact closes a point in a circuit to the drain conductor DR2.

When the interrupter relays are energized during the nineteenth period, master control relays 531 and 533 are energized to complete a circuit through the upper make contacts of relay 529 for short circuiting relay 530. The relay 530, upon restoring, at its upper contact recloses a point in the operating circuit of odd code forming relay 521, at its make before break contacts it again reestablishes a point in its initial operating circuit and interrupts its locking circuit, at its contact 594 closes a point in the knockdown circuit for relay 529, at its lower contacts supplies ground potential by way of the contact and armature 598 and the lower break contacts of relays 525 and 521 to the drain conductor DR2 to operate the drain control relays 333 of any links at this time in the signalling stage of a reverting call connection, and at armature 595 closes a point in the circuit for connecting ground to the pick-up conductor PU.

On the following twenty-second period of operation the master control relay 533 is energized and battery is shunted from the relay 529 by the application of ground potential on conductor 576 through the lower contacts of relay 533 and the contacts 587 and 594 of relays 531 and 530, respectively. Relay 529, upon restoring, at its uppermost contacts closes a point in the operating circuit of relay 521, at its upper inner contacts opens a point in the knockdown circuit of relay 530, at its inner lower make contacts opens its own locking circuit and closes a point in the locking circuit of relay 528, at contacts 596 again closes a point in the circuit for connecting ground potential to the pick-up conductor PU, at armature 598 removes ground from the drain conductor DR2, and at contacts 597 and 598 opens points in the locking and operating circuits of reverse signal alarm relay 552.

When the master control relay 531 energizes in the twenty-third period of the cycle it completes the circuit of the pick-up relay 358 of the finder connector link. This circuit extends from ground at the front contact and armature 588, contacts 596, the back contact and armature 595, pick-up conductor PU, the break contacts of pick-up relay 358, its upper winding, contacts 349, conductor 215, the back contact and armature 297, contacts 292, the front contact and

armature 22 of the test relay 228, and the resistance R24 to battery. The pick-up relay 358, upon operating: at its contacts 359 completes a locking circuit for itself including its lower winding, the contacts 359, 356 and 337, and the grounded conductor 107; at its contacts 365 and 366 connects the armatures 344 and 345 of the ringing relay 343 with the conductors 302 and 303 now connected with the called station, at its contacts 360 and 361 connects the wipers 360 and 317 of the switch CC in circuit with the lower and upper windings of ringing relay 343, so that this relay will hereinafter be operated by ground potential received over either of the wipers 316 or 317. The relay 358 also at its contacts 364 connects the lower winding of the drain relay 333 with the drain conductor DR1 extending to the armature 545 of the interrupter relay 535; at its contacts 363 closes a point in an operating circuit including the upper winding of drain control relay 333, but the closure of these contacts is without effect at this time unless a reverting call has been set up because another point of the circuit is open at the contacts 32 of the busy relay 230; and at its contacts 362 closes a point in the circuit of reverse signal relay 321. The closure of these latter contacts, however, is also without effect unless a reverting call has been set up because the circuit of relay 321 also includes normally open contacts of the busy relay 230, operated on reverting calls.

As will be seen from the code interrupter chart, none of the actual code forming relays are energized during the seventeenth to twenty-fourth periods of the cycle. It will also be appreciated that since during the prior operation of the code interrupter relays CI the pick-up relay 358 was not yet operated and that, therefore, the operation of the interrupter and the code forming relays is without effect so far as the ringing of a subscriber over the shown link is concerned. The signalling of the called station now takes place as the interrupter relays 535 and 534 and the code interrupter relay go through their cycles of operation which follow the operation of the pick-up relay 358.

Since the final digit of the number dialled in the present example is 5, in the described local connection, the wipers 316 and 317 of the class and code switch CC under such circumstances are in engagement with their fifth contacts. As will be seen from an inspection of the code interrupter chart the masking conductor 312 is grounded throughout the first seven periods of operation of the code interrupter relays. This ground potential passes through the bank contact and wiper 317, the contacts 361 and 361', the contact and armature 325, to the upper winding of the ringing relay 343 and battery. The ringing relay accordingly operates and remains operated through the first seven periods of the ringing cycle.

It will also be observed from the chart that during the ninth and through the fifteenth periods of the cycle the masking conductor 311 is continuously grounded, but since the wiper 317 of the switch CC is only in its fifth position the grounding of the masking conductor 311 exercises no control over the ringing relay 343 of the shown link and that therefore the ringing relay will only be energized by current supplied through it when those code forming relays operate which extend ground to the C5 conductor, which, as will be observed from the chart, is grounded during the ninth, eleventh, thirteenth, and fifteenth periods of the ringing cycle. Accordingly the code signal 75

for the line 2645 comprises one long ring followed by four short rings.

It will be observed that, immediately following each ringing period of the ringing cycle, upon restoration of relay 535 a circuit is completed through the drain control relay 333. This circuit extends from ground on conductor 513, through the back contact and armature 545, the drain conductor DR1, contacts 364, the contact and armature 324, and the lower winding of relay 333 to battery. The relay 333 upon each operation opens points in the operating circuits of ring cut-off relay 347 and of relay 229 and connects battery and ground via the back contacts and armatures 345 and 344 and via contacts 366 and 365 to the conductors 302 and 303 during the silent periods of a code to drain potential from these conductors and thereby prevent possible premature operation of relays 347 and 229 by a discharge of the condensers on these conductors, following a ringing period.

The operation of the code interrupter relays during the signalling operation of a reverting call station operate in the same manner as just described; but under these circumstances, owing to the operated condition of the busy relay 230 of the link; the code interrupter relays also complete circuits extending over the drain conductor DR2 and over the reverse signal conductor REV. SIG.

In such a connection during the twenty-fourth period of the cycle during which the pick-up relay 358 is operated, the relay 535 at its armature 545 extends ground potential from conductor 513 through resting contacts and armatures 548, 549 and 555 to the reverse signal conductor REV. SIG. and through the contacts 362, conductor 213, contacts 31, the conductor 214 and the winding of reverse signal relay 321 to battery. The relay 321 accordingly operates to, as previously described in detail, reverse the generator with respect to the called line, operate the ringing relay 343 to transmit a reverting call signal, and to operate the drain control relay 333. The drain control relay 333 is maintained energized through the first period of the second cycle over a circuit including its lower winding, the armature 324 and back contact of relay 321, contacts 364 to ground on the drain conductor DR2 supplied through the armature 591 and front contact of the odd code forming relay 521.

During the first and through the seventh periods of the second cycle of operation of the code interrupter relays the code transmitted to the called station is in accordance with the position of wipers 316 and 317, as in the ordinary connection.

During the eighth period, however, since neither of the mask conductors have ground potential thereon and, during this silent period of the code, the relay 535 again at its armature 545 and its resting contact transmits ground potential over the previously described circuit to the reverse signal relay 321, to again transmit a reverting call signal and to operate the drain control relay 333. The drain control relay is now maintained energized through the ninth period by ground supplied through the lower armature and front contact of odd code forming relay 525.

During the sixteenth period the relay 525 again transmits ground potential over the previously described circuit to operate the reverse signal relay 321, to again transmit a reverting call signal and to operate the drain control relay 333. The relay 333 is now maintained energized through the seventeenth and eighteenth periods by ground supplied through the lower contacts of relay 530

and the front contact and armature 598 of relay 529.

It will be appreciated from the foregoing, that a reverting call ringing signal is transmitted out over a connected called line during the twenty-fourth period of the first cycle and during the eighth, sixteenth and twenty-fourth periods of each succeeding cycle until the call is answered.

Whenever ground potential is removed from the generator start conductor GEN. ST. the relay 620 restores, and at its contacts 625 removes ground potential from conductor 513 and from the connected drain conductor DR1 and reverse signal conductor REV. SIG. The relay 620 also, at contacts 621 opens the circuits of the operated code interrupter and code forming relays, thus allowing them to restore. In addition the relay 620 at contacts 622 opens the locking circuit of relay 627 and the operating circuit of the relays 658 or 658' being at the time employed, thus allowing these relays to restore. The resulting discontinuance of generation of ringing current also allows relay 626 to restore.

The relay 5661 also restores, upon the removal of ground potential from conductor 508 by the deenergization of relay 620, and at its contacts connects the alarm leads of the reverse signal REV. SIG., drain DR1, combination lead 517, mask leads 311 and 312, and drain DR2 to the operating windings of the associated alarm relays, so that an alarm will be given if any of these leads have become permanently grounded, as will be subsequently described.

In case the normally connected pole changing relay 658, for example, fails to generate ringing current, as previously described, the relay 640 operates and applies ground potential to the lower winding of relay 557 via conductor 516. The relay 557 then operates and at its upper contacts applies ground potential to the alarm conductor 314.

In case the code interrupter fails to operate properly, for example should the pick-up lead PU for some reason become grounded, the relay 530, upon operating completes a circuit through the upper winding of alarm relay 557 and this relay will lock up to the pick-up lead via its inner contacts and at its outer contacts grounds the alarm conductor 314 so long as the pick-up lead remains grounded.

In case one of the code combination leads C1—C10 becomes grounded, on the subsequent energization of interrupter relay 534 this ground will feed back over conductor 517 and through the contacts 581 and 5662 to the upper winding of alarm relay 566. This latter relay will accordingly operate and at its contacts 568 locks up to the grounded conductor 517, and at its contacts 569 grounds the alarm conductor 314.

Alarm circuits

In case a fuse associated with any one of the trunk lines blows, then battery through the lower winding of relay 723 of such trunk extends via conductor 705 and through the winding of alarm relay 100 to ground. Both relays 723 and 100 operate. Relay 723 at its contact 786 applies ground potential, via contacts 782, to the trunk test lead 704 to busy the trunk. The relay 100 operates to ground the common alarm lead 314 extending to the non-urgent alarm relay 300.

In case a fuse associated with any link should blow, for example, the fuse shown in Fig. 1, then battery is connected through the upper winding 75

of relay 181, back over conductor 705 and through the relay 100 to ground. The relay 100 will operate as before. The relay 181 accordingly operates and grounds the guard lead 401 to make the 5 link busy to prevent seizure of this link. In a similar manner, if through some fault the reverse signal lead REV. SIG. becomes grounded a circuit will become completed through the lower winding of the alarm relay 566, the front contacts 10 of one of the armatures 548, 549, or 555 of relays 537, 551, or 552, when one of such relays operates. The relay 566 operating under such circumstances, at contacts 567 locks up to the grounded reverse signal conductor.

15 In case the drain lead DR1 becomes grounded, the relay 535, upon operating completes a circuit from ground on this lead through armature 545 and its front contact, and the lower winding of alarm relay 558. The relay 558, upon operating, 20 at contacts 561 locks up directly to the drain conductor DR1 until ground is removed therefrom. If the drain conductor DR2 becomes grounded, a circuit will be completed via the lower break contacts of relays 521, 525, and 529, 25 5663, and through the upper winding of relay 588. This relay will therefore operate and at its contacts 559 lock up directly to the drain conductor DR2 until ground is removed therefrom.

30 In case the masking conductor 311 becomes grounded at a time that its marking relay 537 is deenergized, such ground will flow through the armature 546 and its resting contact, contacts 5666, and through the upper winding of alarm relay 562. This relay will then, via its contacts 35 564, lock up directly to the masking conductor 311. If the masking conductor 312 becomes grounded a circuit will extend via armature 547 and its resting contact, contacts 5665, and through the lower winding of the alarm relay 562. 40 This time the relay will lock up via contacts 565 to the grounded conductor 312.

If the cut-off lead 708 of the relay group TCO should become permanently grounded, the circuit to alarm relay 760 will be completed when 45 relay 752 operates and will lock up through its contacts 651 until relay 752 reoperates after such permanent ground is removed.

If the time pulse lead 707 becomes permanently grounded, the circuit to alarm relay 760 will be 50 closed when relay 756 is at normal. The alarm relay in this case remains locked over the time pulses lead until ground is removed therefrom.

55 When a subscriber fails to hang up his receiver, or in the case of a leak across the line great enough to operate the line relay thereof, such line is considered to be a permanent line. When the link circuit is released and the circuit to the cut-off relay, such as 135, is opened either upon the completion of an incoming call or after the 60 line has been automatically disconnected from the link, upon restoring, at armature 140 opens the circuit to relay 141 and at contacts 136 and 137 connects the line relay 131 to the permanent line. Relay 131, upon operating, at armature 65 133 and its front contact, grounds the test lead 1 to make the line busy, and at contacts 134 closes the locking circuit of relay 141. The relay 141 is, accordingly, maintained operated to prevent the grounding of the start conductor 410 70 extending to the relay allotter, at contacts 144 closes a circuit to the alarm relay 3000, and at contacts 142 prevents the connection to battery through the cut-off relay 135 from falsely marking the line, as a calling line in the finder bank. 75 When the permanent condition of the line is

removed, relay 131 becomes deenergized, and at its contacts 134 opens the locking circuit of relay 141. The relay 131, also, at its armature 133 removes ground from the test multiple 1 to free the line and again connect the cut-off relay 135 5 thereto. The relay 141, upon restoring, at its armature 143 and its resting contact again prepares the circuit for grounding the start conductor 410, at its contacts 142 prepares the circuit for marking the line as calling in the finder relay 10 group, and at its contacts 144 removes ground from the conductor 145 extending to the non-urgent alarm relay 3000.

An operator at the toll or master exchange, desiring to determine if any alarm equipment is 15 operated may extend a connection over the trunk and dial the number required to obtain connection with the alarm line equipment ALE. When the connector bank contacts of this equipment are encountered, and no trouble exists test contact 380 will test idle and interrupted generator will be heard in the same manner as when any other line is called. In case any of the foregoing urgent alarm conditions exist the test contact will have ground potential thereon owing 25 to the operated condition of urgent alarm relay 300, and, accordingly, a busy tone will be received and will serve to indicate the presence of an urgent alarm condition. This condition will also be indicated at the C. A. X. by the 30 lighted lamp UL.

When any line circuit is closed, either by a short circuit or by a receiver being off the hook, the reverting call relay 141 will be energized and the cut-off relay 135 deenergized with the result 35 that the permanent alarm lead 145 will be grounded and the non-urgent alarm relay 3000 will be operated, as previously described. Under these circumstances, when the connector of the link seizes the alarm line equipment, relay 3002 40 will be operated over the circuit including its lower winding, its break contacts, the lower contacts of non-urgent alarm relay 3000, bank contact 378, wiper 377, contact and armature 373 and over the previously traced circuit to ring 45 cut-off relay 347. The relay 3002 accordingly operates and at its inner upper contacts completes a locking circuit for itself including the break contacts of relay 300, conductor 392, bank contact 380, wiper 378, and the grounded conductor 210 of the link. The relay 3002 after completing its own locking circuit opens its break contacts thereby disconnecting its lower winding from the link, and at its make contacts connects dial tone current to the ring and tip conductors 303 and 302 of the link. The operator therefore receives dial tone which advises her of the existence of a non-urgent alarm condition. The absence of any tone indicates to the operator that the tone circuit has failed or that 60 a fuse has blown.

Having described the invention what is considered to be new and is desired to be protected by Letters Patent will be set forth in the following claims:

What is claimed is:

1. In a telephone system, multi-station subscribers' lines, trunk lines, a connector switch having access to said lines, auxiliary means, associated with said connector, controlled by impulses transmitted from the station of a calling line in accordance with a digit of a desired called line to enable said connector to subsequently supply signalling current to the proper conductor of such called line in accordance with the station 75

- being called, means for automatically transferring the control from said auxiliary means to said connector before the final impulse of such digit has been transmitted in case the called digit 5 identifies a trunk call so that at least such final impulse will control said connector, and means for then causing said connector to automatically hunt for an idle one of said trunk lines.
2. In a telephone system, subscribers' lines and 10 groups of trunk lines, a connector switch responsive to a plurality of groups of impulses to extend a connection to contacts in which a desired one of said subscribers' lines terminate; an auxiliary switch associated with said connector, responsive to a group of impulses preceding those 15 transmitted to said connector and effective to determine the path to be employed in subsequently operating the signal on the called line; and means effective when a single group of impulses are transmitted to said auxiliary switch, which group is characteristic only of one of said 20 groups of trunk lines, for switching certain of the impulses of such group to said connector switch to thus bring about the selection of a 25 trunk in a desired trunk line group.
3. In a telephone system, a calling line, a called party line, means responsive to a subscriber on the calling line initiating a call and dialing the first digit of a called subscriber's number for 30 determining the signalling circuit of the station of the line being called, means responsive to the dialling of the next two digits of the called number to extend a connection to the called line, and means responsive to the dialling of the last digit 35 of the called number for determining the signalling code of the called station and for transmitting such code out over the called line providing the same is idle.
4. In a telephone system, a calling line, a called party line, means responsive to a subscriber on the calling line initiating a call and dialling the first digit of a called subscriber's number for 40 determining the signalling circuit of the station of the line being called, means responsive to the dialling of the next two digits of the called number to extend a connection to the called line, means responsive to the dialling of the last digit 45 of the called number for determining the signalling code of the called station and for transmitting such code out over the called line providing the same is idle, a testing circuit over which the called line is tested for its busy or idle condition, and means operated in response to the first 50 impulse of the last digit for completing said testing circuit.
5. In a telephone system, subscribers' lines, a 55 finder connector link including; a finder switch with wipers having access to lines when calling, a connector switch having access to the lines when called, and a combined class and code switch and equipment controlled thereby for determining the class of line called and the ringing code to be transmitted thereto; means responsive to the initiation of a call over any of said 60 lines, for setting the wipers of the finder of said link into connection with the calling line, subscriber controlled means for then consecutively positioning the class and code switch and the connector switch to determine the class of the 65 line being called and to connect the calling line via said link to the called line, and means for placing said class and code switch under control of said subscriber controlled means to enable its operation to determine the character of code 70 to be transmitted over the called line.
6. In combination, an alternating current generator including two pole-changing relays, the operation of either of which may be employed to generate a desired alternating current, means for selectively choosing one of said relays, automatic means for initiating the operation of said one of said relays for the purpose set forth, means operated in case such latter relay fails to function and produce the desired alternating current for transferring said first means into 10 initiative relation to the other of said pole-changing relays, and means for preventing the latter operation occurring if the first pole-changer succeeds in producing the desired alternating current. 15
7. In a telephone system, a calling line, a finder switch in the bank of which the calling line terminates, means associated with said line operated in response to the initiation of a call thereover to place marking potential on one of 20 its line terminals in the bank of said finder and for starting the finder hunting for such marked contact, means for opening said start circuit when the marked contact is encountered, and means for also opening said start circuit in case 25 the finder fails to pick up any marking potential.
8. In a telephone system, subscribers' lines; a group of link circuits, common to said lines, for interconnecting calling and called ones of said 30 lines in talking relation; a group of relays employed by any link circuit, while the same is being employed to interconnect a pair of such lines; means including one of a group of link selecting relays operated in response to the seizure of a calling line by a link to disassociate such link 35 from said group of relays and to associate another link therewith, and means operated in response to more than one of said links being connected to said relay group at the same time 40 to bring about the temporary release from association with said group of all links.
9. In a telephone system, finder switches, groups of calling subscribers' lines having their line and test conductors terminating in the banks of said switches, a group of finder control relays common to said finder switches, a group of marking relays common to said lines; means responsive to the initiation of a call over one of said lines for placing a marking potential on a 45 contact of one of said marking relays in accordance with the line group in which the call originates, for placing marking potential on the test contact of the calling line in the banks of said finders, and for completing a circuit for operating one of said finders and said finder control 50 relays alternately, means controlled by said finder control relays for sequentially operating the marking relays, and a circuit for stopping the sequential operation of said marking relays and 55 the group selecting operation of said finder completed through the marked contact of one of said marking relays.
10. In a telephone system, groups of subscribers' lines, link circuits for interconnecting calling 60 and called ones of said subscribers' lines, a finder switch terminating one end of the link and having two sets of wipers via which the link circuits have access to either of two groups of calling ones of said lines, a connector switch terminating the other end of each of the link circuits and having two sets of wipers via which the link circuits have access to said lines when called; means common to said link circuits, normally associating itself with one of said circuits, 70 75

- and cooperative with such link circuit in response to the initiation of a call to select the wipers having access to the group to which the calling line belongs to operate the finder as required to associate its selected wipers with such group of lines and for then consecutively testing such lines until the calling one is encountered; and means for then disassociating said common means from the link circuit and associating it with another 5 idle one of the group.
11. In a telephone system, groups of lines, finder-connector links common to said lines and in the banks of which line and test terminals of said lines terminate, an allotter common to 10 said links having means for preselecting an idle one of said links, a group of finder control relays and group marking relays associated with said allotter and therefore with any preselected link, means responsive to any link of said group initiating a call for applying marking potential to a 15 contact of a certain of said group marking relays in accordance with the line group in which a calling line is located and for operatively associating said finder control relays with the finder 20 of the preselected link to operate its finder under control of said finder control relays, circuits controlled by said finder control relays for sequentially operating said group marking relays until the marked contacts identifying the group in 25 which the calling line is located have been actuated and the finder positioned opposite such group, means for then positioning the wipers of the finder on the terminals of the first line of the calling group, and an operating circuit for 30 causing the finder to thereafter advance its wipers over the calling line group until the terminals of the calling line are encountered.
12. In a telephone system, groups of lines, a plurality of finder-connector links for interconnecting said lines, a relay group common to said 35 lines and links; means responsive to a line in one of said groups initiating a call for marking such group as calling through the medium of contacts of relays of said relay group, marking such line as calling in the banks of the finders of said 40 links, and for seizing an idle one of said links; means for then transmitting impulses to operate the finder of the selected link until the wipers thereof are positioned opposite the marked calling group, and means for then transmitting impulses from said common means to the finder to 45 move its wipers over test terminals of the lines in the calling group until the marked calling line is found.
13. In a telephone system, two classes of multi-station lines, certain stations of each line equipped with signalling means on one side of their line and others of which have their signalling means on the other side of their line, 50 connector links for establishing connections between stations of said lines, means responsive to the initiation of a call over one line for causing the finder of one of said links to connect with the calling line, operating circuits for 55 the connector switch of such link effective responsive to the transmission of two digits of the called station number to connect the link thereof with the called line, a combined class and code switch in the link controlled by impulse series 60 representing two other of the digits of the called station number; means controlled by said latter switch, when operated during the transmission of one of said other digits, to determine the class to which the called line belongs and also 65 the conductor over which signalling current is 70 to be transmitted to actuate the signal of the called station on such line; and means controlled by said switch, when operated during the transmission of the other of said digits, to determine the specific signalling code to be transmitted and to initiate the transmission of such code providing 75 the called line is idle.
14. In a code signalling system, a pick-up conductor, a plurality of signal conductors, a plurality of current drain control conductors, means for momentarily applying potential to said pick-up conductor and then respectively to the remainder of said conductors in the course of the transmission of a signalling code, and alarm means operated consequent to the failure of removal of such potential at the times intended in the normal operation.
15. In a telephone system, an unattended community automatic exchange, an alarm equipment of such exchange having circuits terminating in 20 the banks of connectors employed in connecting with lines of the exchange and having a number assigned thereto which may be dialled by an operator in a distant exchange in the same manner as when the number of a subscriber's 25 station is dialled in the establishment of a connection, means for transmitting a characteristic tone in case of an urgent trouble, means for transmitting a different tone in case of no trouble, means for transmitting a third tone in case of a 30 non-urgent trouble, and means whereby no tone is transmitted in case of another case of trouble.
16. In a telephone system, multi-station subscribers' lines; means for interconnecting different ones of said lines, means for then selectively code signalling a desired station of the called one of the lines, arrangements enabling the employment of both of said means in the course of establishing communication between two stations on the same line, and means for 40 operating the signal of the calling station in a characteristic manner over only one conductor of the called line so long as the signalling code is being transmitted to the called station over the other conductor of said called line.
17. In a telephone system, a multi-station line, signal equipment for the respective stations comprising ringers in certain cases connected to one conductor of the line and in other instances to the other conductor of said line, the ringers in 50 each instance employing a common ground return path, means including a group of code interrupter relays and a source of ringing current for transmitting coded ringing currents out over a conductor of the line dependent on the station 55 called, and contacts on certain of said code interrupter relays for causing the application of ringing current to the other conductor prior to the transmission of any of the code characteristic 60 of the called station, and at selected periods thereafter during silent periods in the code being transmitted.
18. In an automatic telephone system, party lines, means including connector links controllable over calling lines to connect with called lines, means whereby the subscriber on one of said party lines can seize one of said connectors and operate the same to connect with his own line, means for giving the calling party a busy signal, means responsive to the replacement of the receiver at the calling station for grounding the test conductor of the connector in use, thereby extending holding ground to the release trunk 70 of said connector by way of the private normal 75

of the calling line, means for opening the incoming talking conductors to said connector while the same is maintained by said holding ground, means for signalling the called subscriber in one manner and for operating the signal of the calling station in a different manner

over a conductor of said connector, means for releasing the connector when the calling or the called subscriber removes the receiver, and means individual to the calling line for supplying talking current to the calling and called subscribers.

JOHN E. OSTLINE.
